UNITED STATES PATENT OFFICE

HERBERT M. FRIENDLY, OF CHICAGO, ILLINOIS; MILTON S. FRIENDLY AND CENTRAL TRUST COMPANY OF ILLINOIS EXECUTORS OF SAID HERBERT M. FRIENDLY, DECEASED

TELEPHONE SYSTEM

Application filed October 30, 1922, Serial No. 597,933. Renewed November 12, 1925.

The present invention has for its broad objects the improvement of operating and speech transmission efficiency in toll or long distance telephone systems, particularly where it is desirable to locate the operators remote from the point at which the lines of the toll system enter the toll exchange district. The latter said toll exchange district will usually also comprise a local exchange district as well wherein toll trunking equipments and trunks will be grouped with the corresponding local exchange equipments and trunks.

Where toll lines enter a switching center, which is a large city, geographical conditions are often such that the lines will enter the city from all sides, or at least not all at the same point. Thus, it becomes necessary to either lead all lines through cable or aerial lines to some central point, or to install the manual switchboard at the edge of the city convenient to certain entering lines, and inconvenient to others. In commercial operation this will mean that connections to certain local exchange lines will be prejudiced more than others, depending upon what point in the city local exchange the call terminates. That is to say, for example, if a toll line enters the city at its southern boundary and the central switching office is located at the center, back switching will be entailed if the terminating local exchange telephone of the call is also located near its southern boundary. Where calls are routed through the city, it thus means switching in and out thereof. If the two lines concerned enter at the same boundary back switching will be entailed, and if the lines enter at opposite boundaries, switching across the city will be entailed. Thus, while it may be advantageous to locate the toll switching office in the center of the city for operating reasons due to the placing of originating calls by exchange subscribers, it will not follow that the said central location will be the most economic location when speech transmission factors are considered.

The present invention contemplates locating the toll switching center at the most convenient point from switching operating con-

siderations almost wholly, and then leading the various toll lines entering the city into the most convenient local exchange office or provided toll office near the boundary of the city at which it enters. Thus, the various toll lines of the system entering the city may terminate at widely different points therein, though the operating department will be located centrally without special consideration of speech transmission factors. Each toll line will preferably, though not necessarily, terminate in a switch which has access to trunk lines, or other toll lines. The toll lines are then extended to the central office over conductors which may not be of high speech transmission efficiency. The latter extensions will include control circuits auxiliary thereto of perhaps small gauge cable, or the control circuits may be derived from the said line extensions from the toll line terminating switch to the central office. The said trunk lines accessible to the toll line terminating switches will extend to so-called local toll selectors used exclusively for toll service in the exchange, or they may lead to the general local exchange selectors. Other trunk lines accessible from the said toll line switches may lead around the city border, perhaps aerially, to other offices at which toll lines enter the city and terminate in switches as in the case aforesaid with reference to entering toll lines. Each latter said trunk line will terminate at its far end in a switch having access to the toll lines entering the office at which it is located, and perhaps to trunk lines extending to other offices at which toll lines enter the city, as well as to local exchange toll selectors having access to the selectors of the selector system employed in completing connection from toll lines to local exchange lines, as well as other local selectors, perhaps.

The toll lines terminating in switches may not or may be arranged to permit directive control of the switches over the toll line from the remote end. However, they are preferably arranged so that the calling toll operator at the remote end of the toll line may call the city toll operator over the switch-board extension of the toll line by

signaling along the toll line as if no switch terminated same, to gain the response of the said city toll operator through a jack. The city toll operator can then directly 5 operate the switch on the toll line (located intermediate of the city toll operator and the calling operator on the toll line), to extend the connection from the said switch to another toll line directly, or over a trunk or 10 trunks in tandem, to complete a desired connection. The city toll operator can, if desired, extend the connection from the switch of the calling toll line to a desired local exchange line, so that the connection will 15 be extended in a direct forward path from the toll line to the local exchange line, and not first to the city operator's switching position and then to the wanted exchange line wherein the extension from the toll line terminating switch to the jack on the city toll operator's switching position will be tandem 20 as a link of the connection. It will thus appear that back switching will be wholly or in great part obviated. At least the most direct trunk path (perhaps involving a plurality of trunks) from the entering terminus 25 of the toll line to the wanted local exchange line or wanted toll line, will be taken. The city toll operator will be enabled to supervise 30 the connection audibly and by supervisory signal devices, such as lamps, and also cut the established connection and talk secretly with one end or the other at will, as if the call included a tandem linked path including 35 the switching cord-pair at the switching position of the city toll operator. It also provides for the city toll operator destroying the connection linked through the switches, at will, as by withdrawing the plug 40 from the jack, for example. Where the call is to be extended to a second toll line, the call will route over a trunk or trunks from the toll line terminating switch directly to the wanted toll line, the linking of the latter 45 said connection being remotely controlled by the city toll operator as if the call were destined to a local exchange line.

Provision is made so that the city toll operator may, after responding to a call, set the 50 switch terminating the calling toll line so that the operator at the remote end thereof may directly establish a connection therethrough, enabling the city toll operator to forthwith disconnect from the line before the operator 55 at the remote end of the toll line starts direct operation.

Provision is made so that after the city operator establishes the connection to the wanted line (local or toll), the latter said operator 60 may set the switch terminating the calling toll line so that the operator at the remote end thereof will thereafter control the restoration of the switch terminating the toll line, by way of destroying the established connection. This restoration will be effectuated by

the said remote toll operator disconnecting from the toll line, as by withdrawing the switching plug from the line jack, for example.

Means are provided whereby the operator 70 at the remote end of the toll line can, by applying ringing current in bridge of the talking conductors of the toll line, signal the city operator, without affecting the interposed terminating switches at the city end of the toll line. The city toll operator upon responding, may complete the call from the answering jack through the agency of an ordinary switching cord-pair as a tandem link, or as referred to wherein the terminating 75 switch intermediate of the remote end of the toll line and the city toll operator may be operated to alternatively extend it. Where the latter method is employed, a special jack companion to the answering jack of the toll line is employed. That is, if the call is to be normally forwarded through the agency of the switch terminating the toll line, a trunking jack specific to the toll line will be employed. The plug companion to the answering 80 plug will be employed in connection with the said companion jack. Thus, the city toll operator will perform essentially the same operative movements in extending a call from the toll line terminating switch, located perhaps at considerable distance from the switchboard, as would be entailed in extending the connection through a plug companion to the answering plug and an exchange local toll 85 selector or toll selector having no permanent 90 linked relevancy to the specific toll line. Selectors of the latter class are well known in the art, used to complete connections from any of a plurality of toll lines when temporarily joined with the toll line by an operator's switching cord-pair. However, under the present invention, the calls will not generally be extended through the cord-pair as a link, though as referred to, may be so extended, if desired. Where the call is extended 95 through the agency of the toll line terminating switch to a toll first selector of the exchange, or to a toll selector of the toll trunking system, the switching operator will thus 100 not necessarily know the routing, since the switching operation will not materially differ from that wherein the irrelevant toll selector is employed, only that the specific companion trunking jack will be used. The latter has 105 an operating advantage in obviating the necessity of the operator seeking an idle toll selector which may be common to a plurality of jacks accessible to a plurality of operators.

Having in mind that the foregoing contemplates that calls may be extended from a toll line to exchange lines or to toll lines entering the city at the same point as the calling line or at some remote point therefrom over the most direct trunk route, it will be understood that where a toll line is seized by a trunk 110 115 120 125 130 135

or toll line terminating switch in an outgoing call the switch of the seized line will be rendered disabled so far as being directly operated is concerned. After a response has been attained at the remote end of the called toll line, or before, the connection may be extended from the near end of the said toll line to a local line or to a toll line by the city toll operator inserting the switching plug companion to the one used in the calling, and by operating the calling device directly forward the call to the desired line from the near toll line terminating switch, as if the call had been an originating call from the toll line to the city toll operator. That is, outgoing as well as incoming calls may be completed similarly through the directive extending of the call from the toll line terminating switch.

Auxiliary to the aforesaid mentioned switches terminating the toll lines in the city, are independent pairs of switches extending to a pair of jacks on the city toll switchboard. The said pairs of switches are located in the various toll line terminating offices and have access to bank contacts multiplely with the toll line terminating switches. The latter said switches and the pair of jacks correspond, so that one of the said jacks may be connected with by means of a switching plug of a cord-pair and the corresponding switch directly operated to set its wipers upon a toll line or a toll or an exchange trunk by way of completing a connection to a first called line. Then, the other jack may be connected with through the companion plug of that in the first said jack and the corresponding switch directly operated to set its wipers upon a toll line or a toll or an exchange local toll trunk by way of completing a connection to a second called line, whereby the two said called lines will be connected in talking relation. Of course, both jacks may be connected with before any directive operation. However, signaling over the lines called may be done independently as if the said jacks lead directly to the switches or lines reached by the paired switches. Supervision is accorded the city toll operator as if the talking connection were held through the cord-pair employed as a link, whereas the talking path between the conferees actually exists directly between the paired switches, which may be at a distance from the city toll operator's switchboard and connected therewith with conductors of low speech transmission efficiency. The city toll operator will be enabled to cut an established connection in either direction at will and talk secretly with the maintained end, as if the talking path between the connected lines existed through the operator's cord-pair as a tandem link. The connection will be destroyed at will by the city toll operator. The city toll operator therefore has means auxiliary to the toll line terminating switch whereby toll or local lines

or mixed lines may be paired for talking wherein the link is common to a plurality of lines, but where the city toll operator will perform operative functions as if the cord-pair employed were an actual tandem link. It will be clear, in this connection, that the toll line terminating switches may thus be dispensed with, and the extension of calls to and from the toll lines made through the agency of the independent paired switches located at the various toll line entering offices so as to have access to the toll lines and trunks at the point the toll lines enter. Of course, the arrangement shown wherein the pairs of switches are employed as auxiliary switching agencies makes for more flexible switching.

In order to avoid abstracting excessive current constituting speech from connections, obstructing resistances or resistors are employed in the extensions to the city toll operator's switchboard, but these resistances may be excluded at will, in the event the city toll operator desires to converse over the toll line, or if the toll operator wishes to employ the said extensions as a tandem link of a connection between conferees. The employment of the obstructing resistances will lower the effective electro-static capacity of the cable or other conductors extending towards the city toll operator's switch-board, and thus preventing to a predetermined degree the attenuating of the speech between the conferees where they are connected directly through the switches terminating one of the toll lines, for example, or where the connection is linked by a set of paired switches.

In order to insure the city toll operator knowing definitely what toll line is seized, a back-signaling means is shown in connection with the said paired switches whereby when a toll line is seized, the city toll operator will be apprised by an indicating device of the seized line correspondingly operated by way of sending its specific signal code to the switchboard of the city toll operator directly establishing the said connection. A preferred alternative arrangement is provided whereby in lieu of the indicator visually apprising the calling city toll operator, an indicative tone will be applied to the toll line, audible to the latter said operator when the seizure of the line occurs, directed by the said operator. The indicating arrangements may be applied to the switches terminating the toll lines, but the latter adaptation has not been shown in order to not unduly involve the drawings and descriptions, though it is thought the specific application to any and all switches will be manifest.

Another feature of the invention is embodied in the selector of the local exchange toll trunks, wherein the selector antecedent to the connector is arranged so that the called line can be re-signaled after responding and restoring functions have ensued

thereon. This may be accomplished alternatively by either applying signaling alternating current in bridge of the talking conductors of the connection from the calling end, or by applying directive impulses therefrom, as if a last switch were to be directly operated. Where a number of toll line links are involved in a connection, or where conditions are not favorable to apply operative current of the type stated in bridge of the talking conductors of the connection, the method last mentioned will be employed. However, either stated method of re-signaling may be employed at the will of the calling operator, or other operator to the connection.

Other features and functions of the system of the present invention than those specifically mentioned will appear in the descriptions following:

With reference to the accompanying drawings:

Fig. 1 shows the line, trunk and equipment layout of the system contemplated under the present invention.

Fig. 2 shows a pair of jacks and a leading-out trunk line, together with a cooperative cord-pair A2.

Fig. 3 shows a selector B3 terminating the trunk line shown in Fig. 2, together with an indicating control device H3 individual to an accessible line.

Fig. 4 is a selector C4 terminating the trunk line leading to selector B3, and is inter-linked companion to the selector B3.

Fig. 5 shows a toll line leading to exchange equipment.

Fig. 6 shows a selector D6 terminating the toll line shown in Fig. 5.

Fig. 7 shows a toll line leading to exchange equipment.

Fig. 8 shows a selector E8 terminating the toll line shown in Fig. 7.

Fig. 9 shows a toll line and a toll selector F9 terminating one end thereof.

Fig. 10 shows a toll line and toll selector G10 terminating one end thereof.

Fig. 11 shows a selector H11 terminating the left-hand end of the line shown in Fig. 7.

Fig. 12 shows a well known selector I12 accessible from selector H11, and other selectors of the group containing the selector H11.

Fig. 13 shows a selector K13 accessible from selector I12 and other selectors of the group containing the selector I12.

Fig. 14 shows a well known connector M14 accessible from selector K13 and other selectors of the group containing the selector K13. The connector M14 has access to exchange local lines. In addition to being accessible from selector K13 it is accessible from local selectors of the exchange system as indicated by D' in Fig. 1.

Fig. 15 shows a jack connected to the line leading to selector F9.

Fig. 16 is a switching cord-pair.

Fig. 17 is a diagram showing the assembly of various sheets of drawings to show the joined arrangement of the Figs. to display the equipments involved in the system chosen to elucidate the present invention.

Fig. 18 shows a modification of Fig. 13, introduced where indicated by the reference characters.

Fig. 19 shows a diagrammatic arrangement of trunk selectors F19, S19, N19 and connector C19, the latter having access to telephone T19. The selectors F19, S19 and N19 and the connector C19 are to be assumed as like selectors H11, I12 and K13 and connector M14, respectively. The wipers and bank contacts of the said selectors F19, S19, N19 and the connector C19 have the same numerical designations as the said references, but with a second added, to aid in correlating the corresponding parts.

With further reference to the various figures, the subscriber telephones shown are well known series automatic telephones having well known two-wire dial calling devices. The latter type calling devices are also employed in connection with manual switching equipments.

The selectors shown belong to the general class as shown in U. S. patent to Keith, Erickson and Erickson, No. 815,321, granted March 13, 1906. In the present instance the selectors are modified to operate on the so-called two-wire principle. The automatic rotary feature shown in the selectors is well known in the art, but other features are novel, so far as I am aware.

The off-normal spring sets of the various switches operate upon the first off-normal movement of the shaft carrying the wipers.

In order to avoid undue detailing, when functions are set forth with reference to switching cord-pairs wherein specific keys are provided for listening, signaling and other functions, when the statement is made that a certain condition exists at a stated time, it will be understood that the corresponding key or keys are operated and restored as the condition contemplates, without specifically stating what key operations have been performed by the concerned operator or operators.

The operation of the system contemplated in the present invention will now be detailed with reference to certain assumed calls. Of course, other connections and functions will appear possible beyond those specifically detailed, since only sufficient assumed calls will be detailed as is considered necessary to impart a comprehensive understanding of the operation and scope of the invention.

Referring to Fig. 1, it will appear that the switches B3, C4, D6, E8 and F' have access to bank contacts in corresponding multiple relation. These switches are in a

toll line terminating office, located convenient to the point lines L5 and L7 enter the city, possibly in the office of a city branch local exchange. Jacks J2, J'2, J5, J'5, J7, J'7 and J9 are located on the city toll operator's switchboard. Jacks J5', J7', and J'9 and J15 are located at the remote ends of the toll lines L5, L7, L9, respectively. Jack C' is on the city toll operator's switchboard at the local exchange containing telephone T14, and has a local exchange toll trunk leading to local toll selector B'. The latter said selector has access to local exchange trunks, one of which leads to local toll selector A', which latter selector has access to local exchange trunks, one of which leads to local toll selector K13 in common with selector I12. The selectors A' and B' may be assumed as like selector I12. D' indicates a last local exchange local selector which has access to connector M14 in common with local toll selector K13, it being remembered that the connector M14 is a so-called combination local and toll connector well known in the art. The switch E' terminates a trunk and is located in a toll terminating office in the city, but remote from the office containing switch E8. The office containing switch E' will perhaps have switches like B3, C4, D6 and E8, for example, and it will be related to them as is switch F', the latter said terminating switch being related to a trunk from a toll terminating office as is switch E'. Calls to the office containing the switch E' may thus be made through jack J2, for example. That is to say, switch E' terminates an inter-office trunk between two toll line terminating offices located near different boundaries of the city, perhaps. Of course, the trunks of the latter class will be provided for traffic in both directions between specific toll line terminating offices, and amplified to provide for comprehensive interlinking between all toll line terminating offices, so a call may be trunked from a terminating office at which the said toll line leads-in, through one or more offices over trunk links to a toll line terminating in a different office from the one terminating the originating line. The switches F19, S19, N19 and C19 (the latter one having access to local exchange telephone T19), are all in the same office with switch E8, or may be in different offices of the local exchange. The switches A', B', jack C', local selector D', switch E' and switch F' are indicated to show an amplification of the detailed circuit arrangement shown in the assembly of sheets Fig. 17.

Assume a call from jack J7 to telephone T14. Plug P16 will be inserted into jack J7. A circuit path can be traced from ground, winding of supervisory relay 601', springs 602', 603', 604', springs of key 605' and sleeves of plug P16 and jack J7, spring 701, winding of retardation coil 702, line conductor 703, retardation coil 704, winding

of marginal polarized relay 705, conductor 706, armatures 800 and 801 to the winding of relay 802, the latter said relay actuating, but the relay 705 remaining inert, due to its marginal characteristic. A circuit path can be traced from the winding of slow-releasing relay 803 to the grounded armature 804, the latter said relay actuating, its two upper armatures short-circuiting the obstructing resistances 707 and 708. A circuit can be traced from the winding of relay 710, conductor 712, armature 805 to grounded armature 804, the latter said relay actuating. A circuit can be traced from grounded armature 807 to the winding of slow-releasing relay 809, the latter said relay actuating whereby its armature 810 will ground conductor 811 and attached conductor 812 to guard the line L7 against intrusion by accessible switches.

The actuated condition of relay 710 will cause the polarity at the center point of polarized relay 714 to be changed, it being noted that the said relay 714 and relay 715 constitute opposite polarized relays in a duplex impulse circuit, such as is described in my pending application Serial No. 192,713, filed September 22, 1917. Under the condition of relay 710 becoming actuated, the grounded armature of relay 714 will remain at the normal position shown in the drawings, but relay 715 will attract its grounded armature into engagement with the two working contacts thereof, causing conductor 717 to apply ground to operatively energize slow-releasing relay 101', and conductor 718 to apply ground serially through the winding of marginal relay 102', armature 103' to the winding of relay 104', relays 102' and 104' actuating. Armature 105' will apply ground to conductor 107', causing lamp 108' to glow. The lamp 108' may be located contiguous to jack J7' to serve as a guard signal, or in fact, as a calling signal.

The calling operator will now operate key D16, whereupon relay 601' will be disconnected, and the contacts of the calling device 607' will be substituted therefor. The calling number of telephone T14 is "11211", so if first digit "1" is pulled (effectuating a corresponding one open impulse), relay 802 will operate responsive thereto, causing relays 710, 715, 102' and 104' to deactivate and reactivate resultant thereto, relays 803, 809 and 101' sustaining over the lapse.

The retraction of armature 109' will cause an impulse to be applied to the vertical magnet VM11 in the well known manner, as the selector H11 is a well known type, excepting the present introduction of the relay 102', and the armature 110'. The wipers 111' to 114' will thus rotate-in at the first level, driven by rotary magnet RM11, and seize the first idle set of bank contacts 115' to 118', respectively, relay 120' actuating. The talk-

ing conductors 719—720 of line L7 will thus be continued through armatures 121—122', wipers 113'—114', bank contacts 117'—118', conductors 123'—124' to armatures 201'—202', respectively. The path traced to armature 103' is now continued through wiper 112', bank contact 116', conductor 126', armature 203' to the winding of relay 205', the latter said relay actuating, its grounded armature energizing the winding of slow-releasing relay 207'. Ground on conductor 107' will be applied through armature 130', wiper 111', bank contact 115', conductor 131' to grounded armature 208'. The selector K13 being well known in the art, it need not be detailed. Suffice it to say, however, that upon the calling operator sending the second digit "1", the wipers 211' to 214' will be set upon the first set of idle bank contacts 215' to 218' through the agency of the vertical magnet VM12 and the rotary magnet RM12, after which the relay 220' will actuate to effect the seizure of the latter said selector. The talking conductors 123'—124' are now continued through wipers 213'—214', leading to the terminals 301'—302' of selector K13, respectively. Conductors 126' and 131' are continued to conductors 226' and 231', which lead to armatures 303'—304', respectively. Conductor 718 is thus successively disconnected from the windings of relays 104' and 205', and extended to the winding of low-resistance line relay 305', the latter said relay actuating. When the grounded armature 306' attracts, it operatively energizes the high-resistance slow-releasing relay 307', whereupon the armature 304' applies ground over conductor 231' to bank contacts 215' and 115', wiper 111', armature 130' to conductor 107'. When relay 120' actuates, it causes ground to be applied back from armature 208' over conductor 131' and when relay 220' actuates, it causes ground to be applied back from armature 304' over conductor 231' to conductor 131' before armature 208' retracts. Thus, relays 120' and 220' are held actuated, dependent upon armature 304' and the armatures on polarized relay 715.

Selector K13 is, in general, a well known type of selector as employed antecedent to a so-called combination local and toll local exchange connector. However, the left-hand relay and also the associated equipments designated K'13, together with the circuits associated therewith, are novel, so far as I am aware, and belong to the present invention. The object of the said novel introduced equipments is to capacitate the system so when a call is completed to a called line through selector K13 the signaling thereover will become forthwith initiated automatically, and then said signaling will cease automatically upon the response being attained from the called line. The signaling

can be initiated directly after the called party replaces his receiver, by the calling operator sending digit "2" from calling device 607' at will, to cause the stepping magnet SM13 to advance the associated wipers two steps directly, and then automatically to normal position.

Having in mind that the selector K13 may also be accessible from a toll selector from the local switchboard jack C' over a trunk, in the well known manner, as indicated in Fig. 1, it will appear that applying alternating current, for example, in bridge of the trunk leading to the selector K13 will also serve to re-initiate the signaling upon the called line. Thus, where the call leads over a toll line (as L7) to selector K13, as set forth, the re-initiation of the signaling current will preferably, though not necessarily, be effectuated by sending digit "2", for example, and where the call is from a local toll switchboard jack the re-initiation of the signaling current will preferably, though not necessarily, be effectuated by applying alternating current (or current to which a condenser is transparent, for example) for a brief period from the cord ringing key in bridge of the talking conductors of the trunk. The latter said method cannot be easily carried out where long toll lines intervene, particularly if the said toll lines are composited for impulse transmission.

In view of selector K13 being like well known selectors as to control of the wipers, its operation in extending the connection to connector M14 will be clearly understood. However, when the third digit "2" is sent by the calling operator wherein the stated relays which operated when the first and second digits "11" were sent (with the exception of disconnected relays 104' and 205'), will again operate in the manner as before, and also, the relay 305'. The latter will cause the vertical magnet VM13 to function to raise the wipers 310' to 314' into alignment with the second level of bank contacts. The rotary magnet RM13 will then automatically function to rotate the wipers 310' to 314' into engagement with the first set of idle bank contacts 321' to 325' and seize by reason of relay 330' actuating. The well known combination local and toll connector M14 now terminates the linked connection. The sending of the last two digits "11" will cause the vertical magnet VM14 and the rotary magnet RM14 to respectively function to set the wipers 401' to 403' upon the bank contacts 405' to 407' corresponding to the line leading to telephone T14, and signal upon same in the manner as will appear, presently.

In this connection it will be noted that the relay 102' will vibrate its armature responsive to all operations of the calling device 607', and therefore, after relay 120' actuates. When a response is attained on the

called line wherein the high-resistance winding of relay 307' is substituted for the low-resistance winding of relay 305' consequent to the actuation of relay 331', in the well known manner, the current energizing relay 102' will be attenuated below its operative value, so its grounded armature will retract, whereupon a circuit is closed from said armature on relay 102', armature 110', conductor 132' to the winding of relay 722, the latter said relay actuating. The latter function changes the polarity normally existing at the center point of relay 715, causing relays 714 and 816 to actuate, and lamp 732 to glow to indicate the condition. When armature 800 attracts, it removes the short-circuit normally existing around the resistance 822, so the said resistance is now included in the path energizing relays 601' and 802, it being assumed the key D16 is restored forthwith following the application of the last impulse from the calling device. Due to the marginal adjustment of relay 601', it will deactivate to extinguish lamp 610' as a signal that the party at telephone T14 has responded. The signal constituting the extinguishment of lamp 610' is auxiliary to the signal constituting the glowing of lamp 732, and its multiples. If the party at telephone T14 replaces the receiver, the winding of relay 305' will be substituted for the winding of relay 307', which will augment the current traversing relay 102' to its operative value, which will remove ground from conductor 132', causing the armatures of relays 722, 714 and 816 to retract. The resistance 822 will be thus excluded from the energizing path including the winding of relay 601', so the latter said relay will reactivate to cause lamp 610' to re-glow as a clearing signal.

Returning to the condition at the time the selector K13 seizes, a circuit path can be traced from ground interrupter GI, armatures 332', 333' to the winding of ringing relay 335'. Thus, the latter said relay will cause signaling current to be intermittently applied to the called line in the well known manner, the lower armature of relay 335' making before its upper armature disengages. At the time the party at the telephone T14 responds and relay 331' thereby actuates, followed by the deactivation of relay 305', an operative circuit can be traced from grounded armature 306', armature 337' to the winding of slow-releasing relay 339', cutting off the application of signaling current controlled through the armature 333'. A locking circuit path can be traced from the winding of relay 339', armatures 340', 342', wiper 343', bank contact 344' to grounded conductor 231'. When the receiver at telephone T14 is restored and relay 331' deactuates resultant thereto, a circuit path is prepared from armature 306', armature 337', armature 346' to the winding of stepping

magnet SM13, having in mind that the relay 305' will actuate practically coincident with the retraction of armature 337'; at least armature 306' will be attracted before the stepping magnet SM13 will operate. That is, the cooperative action between relays 331' and 305' is such that as long as the calling operator is maintaining the connection, the traced path including the armature 346' will not operate the stepping magnet SM13. However, if the called party at telephone T14 replaces the receiver and the calling party thereafter pulls the calling device dial to send two impulses, for example, the armature 306' will retract two times, effective to progressing the wipers 348' and 343' two steps into engagement with bank contacts 351' and 352', respectively. The traced locking path for relay 339' will be opened when wipers 348'-343' step to the bank contacts 351'-352', causing the armature 333' to retract to reapply the signaling current to the called line from connector M14. The said wipers 348'-343' will be automatically rotated over the cooperative bank contacts, due to wiper 348' receiving ground from engaged bank contacts, thus returning them to normal position shown in the drawings, due to the interrupter action of the armature on the magnet SM13.

If, in lieu of sending impulses to operate the element K'13 to unlock relay 339', suitable alternating current or other ringing current having an inductive property is applied in bridge of the talking conductors 223'-224', relay 356' will attract its armature 342' to unlock relay 339' to re-apply the signaling current to the called line. Ordinarily, the latter method of unlocking relay 339' will be the most convenient, but where line conditions are adverse to transmitting current of this character of operative strength, the sending of two or more open impulses from the calling device effective to relay 305' will suffice.

If the calling party withdraws the switching plug P16, relays 305' and 307' will deactivate in sequence, causing ground to be removed from conductor 231', unlocking relay 339', armature of polarized relay 715 having restored in advance of armature 304'. However, the re-application of signaling current to the called line will not occur, due to the fact the shaft of selector K13 will be restored, due to an operative circuit path becoming closed from grounded armature 357', armatures 358', 359', spring 360' to the release magnet Re13 before relay 339' retracts its armature 333'. When ground is removed from conductor 231', relay 120' in selector H11 and relay 220' in selector I12 will deactivate, whereupon an operative circuit can be traced in selector H11 from grounded armature 109', armature 135', winding of relay 136', armature 137', spring

138' to the release magnet Re11. In selector H12, an operative circuit can be traced from grounded armature 241', armatures 242' and 243', spring 245' to the release magnet Re12. The connector M14 will restore in the well known manner, due to selector K13 restoring.

A preferred modification of the element K'13 interlinked with selector K13 is shown in Fig. 18. The introduction of the said Fig. 18 into selector K13 will be comprehended in view of the reference designations. In Fig. 18 a step-by-step device GS may be assumed to be a well known so-called "Gill selector", belonging to the general class to which U. S. patent to Gill, No. 906,523, granted December 15, 1908, belongs, and therefore has the function of opening a pair of control springs 801' consequent to the winding of said step-by-step device GS being energized by impulses corresponding to "22", for example, and not open the latter said contact springs responsive to any other directive control. Under the condition of sending digits "22", the relay 339' will become unlocked, causing the called line to be re-signaled. Of course, any combination of digits or series may be employed in lieu of said "22" to effectuate the opening of springs 801'.

If, in lieu of progressing the call through selector H11, the calling operator at jack J7 desires to gain the response of the operator at jack J7', the said calling operator will manipulate the ringing key R16, applying signaling current from source G16 in bridge of the line L7, to operate the drop calling signal device D7'. Upon the operator at jack J7' responding by inserting a switching plug like P16 therein, ground from spring 729 is applied through spring 730 to the winding of relay 722, the latter said relay operating to change the polarity at the center point of relay 715. The latter causes relay 714 to operate to in turn cause lamp 610' to extinguish in the manner before described when party at telephone T14 responded. In this connection, it will be understood that in order to amplify the signaling current applied in bridge of the talking conductors, well known devices may be introduced at the calling and the called ends of the various toll lines.

Assume a call from jack J7' to drop D7. A switching plug like P16 will be inserted into jack J7'. Ground from spring 729 will be applied through spring 730 to cause relay 722 to actuate to in turn cause relay 714 to actuate. An operative circuit can now be traced from armature on relay 714, conductor 723, to lamp 732. Ground on conductor 723 will be applied through armature 815 to the winding of relay 816, the latter said relay actuating. Ground from off-normal spring 820 is applied through armature 821 to the winding of relay 809, which latter relay will

actuate to apply ground from armature 810 to conductor 811, so the line L7 will be guarded against intrusion by accessible switches. The calling operator at jack J7' can now manipulate the ringing key to apply signaling current in bridge of the line L7, effective to drop D7 as a calling signal. Upon inserting plug P16 into jack J7 by way of responding, circuits can be traced as when plug P16 was inserted into jack J7 to initiate a call to telephone T14, the lamp 108' now glowing to indicate the response. It will, however, be noted that due to armature 800 being in its attracted position the resistance 822 will be included serially with the winding of relay 601'. The latter relay, due to its marginal adjustment, will remain normal; as will lamp 610' to indicate the connected condition at calling jack J7'. The calling and answering operators are now in talking relation, the listening keys (corresponding to L16) in the cord pairs being operated. It will be assumed that the calling operator desires the call extended. The answering operator at jack J7 will now insert companion plug P'16 into jack J7'. A circuit can now be traced from the winding of relay 612', spring 613', sleeve of plug P'16, sleeve of jack J7', retardation coil 733, line conductor 734, retardation coil 735, conductor 736, armatures 828 and 829 to the winding of relay 830. Ground applied through armature 828 is also applied operative to high resistance slow-releasing relay 831, but to no operative purpose or object at this juncture, as will appear. Upon the said relays 612', 830 and 831 actuating, armature 832 applies a supplemental ground to the winding of relay 809, and the armature of relay 831 applies a supplemental ground to conductor 811.

Assume that the calling operator at jack J7' desires the call extended to local telephone T19, the calling number of which is "211111". The answering operator will manipulate key K16 to temporarily substitute the calling device 607' for relay 612'. The "2" hole of the dial of the latter said calling device will now be pulled, sending two open impulses to operate relay 830. At each retraction of grounded armature 832, an operative circuit will be closed through armature 833, winding a slow-releasing relay 834, armature 835 to the winding of the vertical magnet VM8, effective to stepping the wipers 837 to 840 into alignment with the second level of bank contacts. The relay 834 will be operatively energized, its armature 841 disengaging make-before-break spring 842 from its resting contact, completing a circuit path from grounded battery, armature 843 on the rotary magnet RM8, winding of relay 845, spring 842, armature 841 to grounded conductor 811, relay 845 actuating and locking through its armature 847 and spring 849. The relay 845 can unlock only if armature

843 attracts, or if spring 849 is disengaged by the selector E8 restoring. After the period of relay 834 following the second impulse to the vertical magnet, armature 841 will retract, whereupon an operative circuit can be traced from the winding of the rotary magnet, springs 842, 849, armature 847 to grounded conductor 811. This will cause the rotary magnet to drive the wipers 837 to 840 one step into engagement with the first set of bank contacts 851 to 854. The upper terminal of relay 856 is tied to grounded conductor 811, and the lower winding terminal thereof is grounded to said conductor 811 through armature 847, upon relay 845 actuating. However, upon the armature 843 attracting incidental to driving the wipers, relay 845 will retract its armature 847 so that the lower winding terminal of relay 856 now has the winding of relay 845 and grounded battery at armature 843 connected serially therewith. The relay 856 will actuate to effect the seizure of selector E8, though relay 845 will remain inert due to its marginal characteristic. Had wiper 837 encountered busy ground on bank contact 851, this ground applied through armature 852 to the lower winding terminal of relay 856 will serve to short-circuit it and also apply the said ground through spring 849, winding of relay 845, armature 843 to grounded battery, causing relay 845 to reactuate and lock, and also operatively ground the rotary magnet by way of spring 842 to advance the wipers off the first set of bank contacts into testing engagement with the succeeding set of bank contacts, the operation continuing until wiper 837 fails to receive ground.

The answering operator will next annex the last five digits "11111" to extend the connection from conductors 857 to 860 to the called telephone T19, the selectors F19, S19, N19 and connector C19 successively functioning in view of the references.

At the time the shaft of selector E8 steps off-normal, the spring 820 opens the local ground from the winding of relay 809, the armature 832 still maintaining said relay 809 operatively energized. However, when the said selector E8 seizes, relay 830 is disconnected at armature 829 on relay 856. The conductor 736 is thus conductively extended over conductor 858 to the impulse relays of selectors F19, S19, successively, and finally to the corresponding relay in the selector N19. The conductor 857 receives ground from ahead in the well known manner, in view of the citations, to maintain relay 856 actuated. Upon response of the party at telephone T19, the current traversing conductor 736 is attenuated below the operative value of relay 612' (the key D16 having been previously restored), so the lamp 614' extinguishes as an answering signal. In view of relay 856 being actuated and locked through armature 852 from ground received back from conductor 857, bank contact 851, wiper 837, the talking path from the line L7 is continued through armatures 855—856, wipers 839—840, bank contacts 853—854, conductors 859—860 and through the talking paths of the succeeding switches to telephone T19. That is to say, the calling operator at jack J7' and the answering operator at jack J'7 (and J7) are commonly in talking relation with telephone T19. The answering operator may disconnect the operator's telephone set T16, leaving the calling operator at jack J7' and the called party at telephone T19 in talking relation. The restoration of the switches involved in the extended connection is under control of the answering operator at jacks J'7 and J7, who will be apprised when the called party restores the receiver, due to the fact the current in relay 612' will be then augmented to its operative value to cause the lamp 614' to glow as a clearing signal. The withdrawal of plugs P'16 and P16 from jacks J7 and J'7, respectively, will cause ground to be removed from conductor 857 from the selector N19. This will cause all the antecedent switches to restore in the well known manner in view of the present invention. The connector C19 will restore incidental to selector N19 restoring. For example, an operative circuit can be traced from armature 832, armature 833, winding of relay 834, armature 835, off-normal spring, to the release magnet Re8. In view of the last described functioning, it will be clear that the control of the switches involved in the extended call is from the jack J'7, and therefore, if the answering operator desires to efface an extended call at any time, simply withdrawing the plug P'16 from jack J'7 will accomplish it, after which it may be re-inserted and the call thereafter extended as a new call, the plug P16 having been previously withdrawn from jack J7.

Having in mind that plugs P16 and P'16 are inserted in jacks J7 and J'7, respectively, as if the call were being linked through the cord pair, to all intents, so far as the operator is concerned, if the answering operator now desires to talk with the called party at telephone T19 secretly against the calling operator at jack J7', key B16 will be operated, applying high-voltage plus battery through spring 603', sleeve of jack J7, over conductor 706 to the winding of relay 802, operative to attract the grounded armature of relay 705 to the right hand working contact, operatively energizing relay 745. This will disconnect talking conductors 746 and 747 from line L7 and apply them to conductors 734 and 703, respectively. The current applied from key B16 will cause the flow in the winding of relay 802 to be reversed, but to no operative object so far as said relay 802

is concerned. The answering operator can alternatively operate key B'16 and apply high-voltage minus battery through springs 602' and 603' and over conductor 706, operative 5 to attract the grounded armature of relay 705 to the left-hand working contact, operatively energizing relay 750. This will disconnect the talking conductors of line L7 from conductors 746 and 747, and apply them 10 to conductors 734 and 703, respectively.

After the calling and called parties have started to converse, the answering operator may withdraw plug P16, and thereby cause relays 802 and 803 to deactuate, removing the short-circuit from resistances 15 707 and 708, so the leg from line L7 extending to the jacks J7 and J'7 will not abstract appreciable current constituting the speech between the correspondents, and at 20 the same time permit the answering operator to know by listening-in that the conversation is proceeding. A key 605' is provided for opening the sleeve conductor of the plug P16, so the answering operator may 25 operate the latter said key to deenergize relay 803 at will, without withdrawing plug P16, in the event it may be desirable to again converse with one or both of the correspondents, as otherwise it would be necessary to re- 30 insert the plug P16 into jack J7 in order to exclude the resistances 707 and 708 by causing relay 803 to actuate. That is, operating key 605' (with plug P16 in jack J7) will cause the resistances 707 and 708 to be included, and restoring key 605' thereafter will cause the resistances 707 and 708 to be again excluded.

The answering operator will have clearing supervision from the called telephone T19 40 through the agency of lamp 614', and similar supervision from the calling jack J'7, through the agency of lamp 732. The extension of the connection through selector E8 to the called telephone T19 will sustain if only 45 plug P'16 is withdrawn from jack J'7 wherein ground will be removed from conductor 736 extended as the leading-in impulse conductor for selector N19, since when plug P16 is in jack J'7 the relay 802 will be actuated, causing ground to be maintained on conductor 811. The selector N19, and antecedent selectors, will be maintained seized dependent upon ground being maintained on 50 conductor 811. When plug P'16 is withdrawn ground is no longer applied over impulse conductor 736. Thus, connector C19 is now subject to restoration responsive to the receiver at telephone T19 being restored, 55 while selector N19, and antecedent selectors, are maintained subject to conductor 811 remaining grounded, in control of plug P16.

If plug P16 is withdrawn while the receiver at telephone T19 is maintained off the 60 switchhook, selector N19, and antecedent se-

lectors, will restore, whereupon the connector C19 will also restore consequent thereto.

It will be clear that while the calling operator at jack J7' is not enabled to directly operate the selector E8, when a plug is inserted into jack J7', conductor 811 is caused to become grounded to guard the private bank contacts corresponding to the line L7 against intrusion, and at the same time cause lamp 732 before the answering operator, and other operators, to glow as a busy signal. It will be manifest that the answering operator does not know the physical location of the various equipments, and for operating purposes may consider the jack J'7 a trunking jack independent of the line L7, but employed exclusively in extending connections from line L7 to obviate being required to look for a disengaged trunk common to other operators and other toll lines. Of course, jacks J7 and J'7 may be multiplied so the line L7 may be thus responded to or connected with by any of a plurality of operators. The jack J'7 is for extending calls, while the jack J7 is for cutting off either the calling or the called section from the other while maintaining a talking connection from jack J7 to the section not cut off.

Assume the calling operator desires the call extended to jack J10, the calling number of which is "11", in lieu of to telephone T19. The call will be extended by the answering operator through the agency of the plug P'16 and jack J'7 in the manner generally as described wherein the call was extended to telephone T19. Responsive to the sending of the first digit "1" from plug P'16 through jack J'7, the said wipers of selector E8 will rotate-in on the first bank level and seize the first idle set of bank contacts 861 to 864, leading over conductors 865 to 868, respectively. The conductor 865 will become grounded from conductor 811 and thus cause a busy ground to be placed upon all private bank contacts corresponding to 861 of accessible switches. Ground is applied through relay 612' over conductor 736, armature 828, wiper 838, bank contact 862, conductor 866, the center point of the line winding of repeating coil C9, conductors of line L9, center point of line winding of repeating coil C'9, conductor 901, armature 902 to the winding of relay 903, the latter said relay actuating, its armature 905 applying ground through conductor 906 to the winding of relay 907, the latter said relay actuating. Armature 910 will apply its ground to the winding of slow-releasing relay 912, causing the latter said relay to actuate, its armature 913 applying ground to conductor 914. Armature 916 prepares a circuit path from the winding of slow-releasing relay 918 to the vertical magnet VM9. The grounding of conductor 914 places a busy ground on all switches acces-

sible to line L9 at the end remote from selector E8.

Upon the answering operator sending the second digit "1" whereby an open impulse will be applied to conductor 736, effective to causing relay 903 to deactivate and reactivate one time, which in turn, will cause relay 907 to similarly function, armature 910 applying a ground impulse through armatures 919, 10 winding of relay 918, armature 916 to the vertical magnet VM9. The shaft carrying wipers 921 to 924 will be stepped into alignment with the first bank level. When relay 918 energizes, its armature 927 applies ground from conductor 914 to make-before-break spring 928, winding of relay 929, armature 932 on rotary magnet RM9 to grounded battery, the said relay 929 actuating and locking through off-normal spring 933, armature 934 to conductor 914. Thus, the relay 929 will remain actuated until armature 932 attracts or the off-normal spring set ON9 restores. When armature 927 retracts the period of relay 918 after the armature 910 re-attracts, an operative circuit is closed from the winding of the rotary magnet RM9, springs 928, 933, armature 934 to grounded conductor 914, the rotary magnet operating to rotate the wipers 921 to 924 into engagement with bank contacts 941 to 944, respectively. Bank contact 941 being assumed ungrounded, the short-circuit to ground from the lower terminal of the winding of relay 947 will be removed when armature 934 retracts, because wiper 921 will not receive ground to be applied through armature 949 to the winding terminal of relay 947 which is tied to armature 934. The relay 947 will thus operatively energize in a path from conductor 914, spring 933, winding of relay 929, armature 932 to grounded battery, the armature of relay 929 remaining retracted due to its marginal adjustment. The selector F9 is thus in a seized condition, relays 907 and 912 deactuating in sequence. Before relay 912 has had time to retract its armature 913, armature 906 applies the traced path from armature 905 through wiper 922, bank contact 942, conductor 950 to the winding of relay 3, the latter said relay 50 actuating, slow-releasing relay 4 being operatively energized from grounded armature 5, so that armature 6 will apply its ground over conductor 7, bank contact 941, wiper 921, armature 949 to conductor 914. Relays 856 and 947 being maintained actuated to hold the selectors E8 and F9 seized, an operative circuit path can be traced from grounded armature 10, armature 12, center point of line winding of repeating coil C10, conductors 60 of line L10, center of line winding of repeating coil C'10, spring 14 to the winding of relay 15, armature 17 closing a circuit to glow lamp 18 as a calling signal to the operator at jack J10, and which may be responded to by 65 inserting a plug like P16 into jack J10,

whereupon the winding of relay corresponding to 801' will be substituted for the winding of relay 15, having in mind the latter said relay is applied to ground while the former said relay is applied to grounded battery. 70 The lamp 18 will extinguish.

At the time selector E8 seized, wherein relay 912 in selector F9 actuated to ground conductor 914, this ground is continued through armature 501' to the winding of relay 502', the latter said relay actuating to disconnect the line drop D15 and to cause busy lamp 503' to glow. The jack J15 will be disconnected by armatures 505' and 506'. 75

The calling operator at jack J7' is now in 80 talking relation with the operator at jack J10. The connection beyond the bank contacts seized by selector E8 can be destroyed by the answering operator withdrawing plug P'16 from jack J7'. The latter would normally occur after the toll conversation terminates, supervised by the said answering operator. If it is desired to destroy the connection including the restoration of selector 85 E8, plug P16 will be withdrawn from jack 90 J7, also, or alternatively, key 605' may be operated to open the path traced over conduction 706 for a sufficient time to allow relay 809 to retract its armature 810 so relay 856 will deactivate to close the path traced 95 from armature 832 to the release magnet Re8, and also to operate the release magnet Re10 as will appear, presently.

In special instances, it may be desirable to have the said answering operator directly 100 establish the connection as described, and then set the circuits so the calling operator can control the destroying of it, the said answering operator, withdrawing plugs P16 and P'16 after the operator at jack J10 responds. Before removing the latter said plugs, key 755 will be momentarily pressed to lock relay 756 to conductor 811. This will cause armature 758 to close an operative path from conductor 723 to the winding of relay 110 760, whereby armature 762 will apply ground to conductor 736 in multiple with the ground applied through the winding of relay 612'. When the plug P'16 is withdrawn, ground will thus remain on conductor 736 to maintain relay 3 energized. When the calling operator removes the plug from jack J7', the armature of relay 714 will attract to the left to deenergize relay 760, whereby ground will be removed from conductor 736, followed by ground being removed from conductor 811 to unlock relay 756. 115

In view of the last foregoing statements, it will appear that if the said answering operator presses key 755 and then withdraws plugs P16 and P'16, just after directly setting the wipers of selector E8 upon the cooperative bank contacts, the further progression of the call, as when the call was destined to telephone T19, will be in direc- 123 130 135

tive control of the calling operator through the agency of calling device 765, the key 766 being depressed to change ground on spring 729 to the calling device 765. Under the 5 latter condition, the armature on relay 760 will vibrate responsive to the calling device 765 to apply open impulses to conductor 736 as if controlled through the plug P'16 from calling device 607'. It will also be manifest 10 that forthwith after responding, the said answering operator may press key 755 and then withdraw plug P'16, after which the progression of the call through selector E8 and successive switches, perhaps, will be under 15 the control of the calling operator at jack J7'. The destroying of the latter said directly established connection, for example, will also reside in the plug in jack J7'. It will be noted, in this connection, that under 20 the latter said condition, the destroying of an established connection will cause the locking path for relay 756 to be opened so a new call from jack J7' will be barred from directly operating the selector E8. A modification by way of slugging relay 760, or by 25 simply adjusting it to respond sluggishly, will operate to bar switches from being directly operated from jack J7' because said relay 760 cannot then vibrate responsive to 30 the calling device 765.

When the circuits are normal, a switching plug, such as shown in Fig. 16 may be inserted into springjack J9 and signaling current applied in bridge of the line L9, and 35 conductors 961 and 962 thereof, to operate the drop D15. Upon response, by inserting a plug similar to P16 into jack J15, an operative circuit path can be traced from grounded spring 510', armature 512' to the winding 40 of relay 513'. The latter function causes drop D15 to be disassociated and armature 501' applied to ground to place a busy guard on the private bank contacts corresponding to line L9. The ground applied to the sleeve 45 of the jack J15 from the cord relay corresponding to 601' will be conducted through armature 515', conductor 516' to the winding of relay 955, armature 956 applying its ground to operatively energize slow-releasing 50 relay 958. Grounded armature 959 applies its ground through armature 902, conductor 901, conductors of line L9 to conductor 866. That is, if a switch similar to F9 is assumed as related to the right-hand 55 end of line L9 as switch F9 is related to the left-hand end thereof, the call could be directly progressed from the jack J15 through the agency of the calling device corresponding to 607' associated with the 60 plug in the jack J15.

Assume it is desired to extend a connection from jack J10 to jack J9. A switching plug P16, for example, will be inserted into jack J10. A circuit path can now be traced from ground through winding of relay 601',

sleeve of plug P16, sleeve of jack J10, spring 20, center point of line winding of repeating coil C'10, conductors of line L10, center point of line winding of repeating coil C10, armature 12 to the winding of relay 23, the latter said relay actuating. Ground is now applied through armatures 25 and 26 to the winding of relay 27, the latter said relay actuating. Grounded armature 30 will energize slow-releasing relay 31, so armature 33 will apply its ground to conductor 7 and attached private bank contacts of accessible switches, such as F9, for example. 70 75

Upon the key D16 being operated and the calling device 607' being pulled to effectuate one open impulse, relay 23 will deactivate and reactuate one time, causing relay 27 to similarly function. Having in mind the selectors F9 and G10 are similar, it will be clear that the vertical and rotary magnets of selector G10 will operate wipers 41 to 44 so they will be set upon bank contacts 51 to 54, respectively, and the selector will seize. That is to say, conductors 58-59 of line L10 will be continued through armatures 60-61, wipers 43-44, bank contacts 53-54 to conductors 962-961 of line L9, respectively. Under the seized condition of selector G10 the circuit from armature 25 is continued through armature 26, wiper 42, bank contact 52, conductor 516' to the winding of relay 955, the latter said relay and its dependent relay 958 actuating. Ground from armature 965 is applied over conductor 914, bank contact 51 and attached private bank contacts accessible to guard the line L9 against intrusion and to discontinue drop D15 and jack J15. The ground from bank contact 51 is applied through wiper 41, armature 65 to conductor 7 before armature 33 will retract because of relay 27 being disconnected due to relay 70 actuating. This will therefore maintain the selector G10 seized, by reason of maintaining relay 70 energized. The relay 955 will remain energized dependent upon relay 23, and the latter relay will, in turn, be maintained dependent upon the plug P16 remaining in jack J10. The calling operator at jack J10 is now in talking relation with jack J9, assuming, of course, that proper keys of the calling cord-pair have been operated. 90 95 100 105 110 115

If it is assumed that the right-hand end of line L9 has a selector like F9 connected thereto in the manner selector F9 is shown connected to its left-hand end, annexing digits by the manipulation of the calling device 601' will directly operate the latter said assumed selector by way of extending the call therethrough. Withdrawing plug P16 from jack J10 will cause the winding of relay 15 to be substituted for the winding of relay 601', so the relay 23 will deactivate, causing the ground to be removed from conductor 7, resultant to causing relay 70 to deactivate. An operative circuit can now be traced from 120 125 130

grounded armature 30, armature 72, winding of relay 73, armature 74, spring 76 to the release magnet Re10.

- Assume a call from jack J5 to jack J5'.
 5 Plug P16 will be inserted into said jack J5', whereupon an operative circuit path can be traced from ground, winding of relay 601', springs 602', 603', sleeve of plug P16, sleeve of jack J5, spring 501, winding of low-
 10 resistance marginal polarized relay 503, conductor 504, armatures 601 and 602 to the winding of relay 603. Armature 605 will apply its ground over conductor 606 to the winding of slow-releasing relay 607, the latter
 15 said relay actuating. Armature 609 will apply ground to conductors 611 and 612 to guard the line L5 against intrusion by accessible switches. Armature 614 will operatively energize slow-releasing relay 615.
 20 The two upper armatures on relay 615 will short-circuit obstructing resistances 507 and 508, respectively. The armature 616 removes the normal short-circuit from resistance 617. Pressing ringing key R16 will apply source
 25 G16 in bridge of the talking conductors of line L5 operative to the calling drop D5'. The call can be responded to by inserting a plug like P16 into jack J5'. The drop D5' will be disconnected and a circuit path can be traced from ground through relay corresponding to 601', sleeve of plug, sleeve of jack J5', center of line winding of repeating coil C5, over the talking conductors of line
 30 L5, center of line winding of repeating coil C5', conductor 510, resistance 617, armature 618 to the winding of slow-releasing relay 619, the latter said relay actuating, including resistance 621 into the path of conductor 504. The relay corresponding to 601' will
 35 remain inert, due to its marginal characteristic, since resistance 617 is included in the energizing path from the winding of relay 619 to the said relay corresponding to 601'.
 40 Thus, the lamp 610' and the one corresponding thereto associated with the plug in jack J5' are not glowing, due to their respective marginal controlling relays being inert.
 Assuming that the calling and the called
 45 operators have manipulated the listening keys of the respective cord pairs employed, the operators are in talking relation. Should the calling operator withdraw the plug P16 first, relays 603 and 615 will deactivate in sequence, armature 616 short-circuiting resistance 617 to augment the current strength in the said relay corresponding to 601', associated with the plug in jack J5' to its operative value, so the lamp corresponding to 601' associated with the latter said relay will be caused to glow as a clearing signal to indicate the condition. Should the called operator withdraw the plug from jack J5' first, relay 619 will deactivate, its armature
 55 601 short-circuiting resistance 621 to augment the current traversing relay 601' to its opera-

tive value to glow the lamp 610' as a clearing signal to indicate the condition.

Assume that when the called operator answers the call by inserting the plug into jack J5', the said called operator at jack J5' 70 requests the connection extended to jack J7', the calling number of which is "3". The plug P16 will be left in jack J5 and plug P'16 will be inserted into jack J5'. A circuit path can now be traced from ground, winding of relay 612', spring 613', sleeve of plug P'16, sleeve of jack J5', conductor 515, armatures 624 and 625 to the winding of relay 626, the latter said relay actuating. High-resistance slow-releasing relay 627 is legged from conductor 515, so its armature will attract to apply ground to conductor 611. Grounded armature 628 will thus apply supplemental ground to the winding of relay 607, which will insure the relay 607 remaining actuated when the 80 shaft of the selector D6 steps off-normal and opens the ground to conductor 606 at spring 629, established when relay 619 actuated, regardless of the plug being maintained in jack J5, to in turn maintain relays 603 and 605 90 actuated wherein armature 605 applies its ground to conductor 606. That is to say, when the shaft steps off-normal, the control of the restoration resides in the operator at jacks J5 and J5', whereby withdrawing the 95 plugs from jacks J5 and J5' will cause relays 603, 615, 607 and 627 to retract their armatures to remove ground from conductor 611 to cause the shaft to restore, as will appear, presently. Withdrawing plug P16 will remove ground from conductor 504, causing relays 603 and 615 to deactivate, while removing plug P'16 will remove ground from conductor 515, causing relay 626 (and 627) to deactivate, followed by relay 607. 100

Returning to the condition of the circuits upon the said insertion of plug P'16, it will be clear that sending open impulses over conductor 510 from jack J5' will have no operative effect, due to the slow-releasing characteristic of relay 619. However, if key D16 is operated and the sending device 607' is pulled to effectuate three open impulses, relay 626 will deactivate and reactivate three times responsive thereto, armature 628 sending three ground impulses through armature 630, winding of slow-releasing relay 631, armature 632 to the vertical magnet VM6, the vertical magnet correspondingly operating to step the shaft carrying wipers 635 to 638 into alignment with the third level of bank contacts. At the time relay 631 energizes, its armature 639 attracts to apply ground from conductor 611 through make-before-break spring 640 through the winding of relay 642, armature 643 on the rotary magnet RM6 to grounded battery, relay 642 actuating, its armature 645 closing a locking path for said relay 642 from conductor 611, spring 647, 115 winding of said relay 642, armature 643 to 120

grounded battery. Upon armature 639 retracting, following the last impulse to the vertical magnet, a circuit can be traced from the winding of the rotary magnet, spring 640, 5 spring 647 to conductor 611, the rotary magnet actuating to advance the said wipers 635 to 638 into engagement with the first set of bank contacts 651 to 654, respectively. Provided wiper 635 does not receive busy ground 10 from bank contact 651, no ground will exist on the lower winding terminal of relay 658 when armature 645 retracts, due to armature 643 attracting to deenergize relay 642. Under this condition of armature 645 retracting, 15 the battery applied through armature 643 energizes relays 642 and 658 in series to conductor 611. However, due to the marginal characteristic of relay 642 relay 658 only will 20 actuate to effect the seizure of selector D6. If wiper 635 encounters ground on bank contact 651, when armature 643 retracts, relay 642 will operatively energize through spring 647, armature 660, wiper 635 to its engaged 25 bank contact, so the rotary magnet will become energized over the previously described path to drive the wipers to test the next set of bank contacts, the automatic rotating function continuing as long as wiper 635 receives ground from an engaged bank 30 contact.

Going back to the condition of the circuits upon relay 658 actuating, it will appear that under the seized condition of selector D6, the winding of relay 626 will be disconnected, but 35 due to the plug P16 being in jack J5 relay 603 will remain energized to maintain ground to the winding of relay 607 so that the conductor 611 will remain grounded, and relay 615 will remain actuated. Ground from conductor 611 will be applied through armature 660, wiper 635, bank contact 651, conductors 812 and 811 to busy guard the line L7 against seizure by an accessible switch. Ground on conductor 811 can be traced through armature 870, to the winding of relay 871, the latter said relay actuating. Armature 828 opens conductor 736 to prevent relay 830 being vibrated from jack J7', and armature 801 opens the path from the sleeve of jack J7 45 to the winding of relay 802. Thus, if an operator inserts a plug into jack J7' or J7, the obstructing resistances 707 and 708 will be included in the listening path since relay 803 will be deactuated. Also, the supervisory 50 lamps (corresponding to 610' and 614') associated with the plug in the jack or jacks J7' and J7 will glow to indicate the busy condition. However, due to armature 815 being attracted against its grounded make contact, 55 conductor 723 will apply this ground to lamp 732 as a busy signal or guard, so the operator will know the busy condition before inserting a plug into one of the latter said jacks. Conductor 515 will be applied through armatures 624 and 625, wiper 636, bank contact 652, 60

conductor 666, armatures 872, 805, conductor 712 to the winding of relay 710. That is, relays 612' and 710 will be operatively energized in series. The armature on relay 715 will therefore apply ground to conductors 717 and 718 (the lamp 108' glowing as a calling signal), and to operatively energize relays 102' and 104', as well as relay 101' in the manner before described in a call from jack J7'. 75

It will be clear that if the said operator at jacks J5 and J5' manipulates key D16 and the calling device 607' to annex one open impulse, relays 710, 715, 102' and 104' will respond to set the wipers 111' to 114' upon the first idle set of bank contacts of the first level in the manner before described. The call can thus be directly extended to telephone T14, for example, by annexing digits as before employed for this function. Of course, the latter said operator can, if desired, manipulate key B16 to apply high-voltage plus grounded battery through the winding of relay 503, effective to attracting the armature thereof against its right-hand contact to 80 operatively energize relay 521 to cut the extension of line L5 leading from jack J5', and then applying signaling current from key R16 in bridge of the talking conductors 522-523 over the path to be presently traced, 85 to operate the drop D7'. Upon the called operator responding by inserting a plug like P16 into jack J7' and the operator restoring key R16, and both the said operators having 90 their cord listening keys operated, a talking path can be traced from operator's set T16, plug P'16, jack J5', inside armatures of relay 521, conductors 522-523, armatures 662-663, wipers 637-638, bank contacts 653-654, conductors 670-671, 876-877, 746-747, 95 inside armatures of relays 745 and 750, respectively, repeating coil C7', line L7, repeating coil C7, conductors 719-720, jack J7' to the operator's set associated with the operating switching plug. Had the connection 100 been directly extended through the before stated switches to telephone T14, the talking path as advanced from conductors 719-720 would be as before traced. 105

In order to place jack J5' in talking relation with jack J7', key B16 will be restored, whereby relay 521 will deactuate to continue the talking path through the inside armatures of relays 521-525, respectively, repeating coil C5', line L5, repeating coil C5, jack J5' to the operator's set associated with the cooperating switching plug. Having in mind that plug P16 is in jack J5, it will be manifest 110 relays 603 and 615 will be actuated and the obstructing resistances 707-708 short-circuited so the operator at jack J5 will hear normally and abstract considerable current 115 from the talking path between the correspondents connected through jacks J5' and J7', respectively. The capacity of the con- 120 125 130

ductors involved in the leg to jacks J5 and J'5 will also affect the strength of speech between jacks J5' and J7'. The operator, by withdrawing plug P16 from jack J5 will cause relay 615 to deactivate to remove the short-circuit from the resistances 707-708, respectively, so the strength of speech current abstracted from the direct path between jacks J5' and J7' will be the minimum, in view of the resistances 707-708. The selector D6 and the extended connection will be maintained under control of the plug in jack J'5, due to conductor 812 being maintained grounded from the armature of slow-releasing relay 627. The latter said relay has a preferably high resistance winding legged from conductor 515, so that while conductor 515 is grounded through the sleeve of jack J'5 to the winding of relay 612', ground will be maintained on conductor 612. The relay 627 will thus independently ground conductor 611, though the armature 609 of relay 607 will also ground conductor 611 under conditions hereinbefore described. The resistance value of the winding of said relay 627 is high enough to not appreciably affect the current flow on conductor 515 in view of described marginal relay control thereover. It is preferable to have relay 627 slow-releasing so as to obviate its vibrating while control impulses are being sent over conductor 515 from the calling device. Relay 831 in selector E8 corresponds in its operative object to relay 627 in selector D6. It is thus clear that after a response is obtained at jack J7' the plug P16 may be withdrawn from jack J5 to introduce resistances 507-508, the linked connection through selector D6 being maintained dependent upon withdrawing plug P'16. The latter function will cause relay 627 to deactivate to remove ground from conductor 611, wiper 635, bank contact 651, conductors 812 and 811. The latter grounded condition maintained relay 658 in selector D6 and relay 871 in selector E8 actuated.

A resistance 770 normally shunts the winding of relay 716 to battery on spring 771, so enough current will traverse the winding of relay 601' to maintain lamp 610' glowing. However, when relay 714 operates responsive to the actuation of relay 722, due to a response from the jack J7' or from telephone T14, as the case may be, the shunt resistance 770 will be opened from around the winding of relay 710 so the current strength traversing the winding of relay 601' will be reduced below its operative value to extinguish lamp 610' as an answering signal. Lamp 610' will then glow upon the relay 714 restoring to normal when the called party connected over line L7 restores. It will be understood, in this connection, that operating key B'16 will apply high-voltage minus battery through the winding of relay 503 so its armature will ground the winding of relay 525 to cut off the talking connection through selector D6, so the operator at jacks J5 and J'5 may talk secretly through either said jack J5 or J'5 to the calling operator through jack J5'. When either relay 525 or 521 is operated, the resistances 507-508 are excluded from the talking path extending to jacks J5 and J'5.

It will appear from the drawings that selectors E8 and D6 have corresponding trunks and toll lines. Moreover, the general operation of the latter said selectors have been detailed, so it is thought that the operation of the selector D6 when employed in extending a connection to telephone T19 or over line L9, will be clearly understood in view of the descriptions of calls to telephone T19 and line L9 through the selector E8. However, attention is called that continued seizure of selector D6 is dependent upon maintaining a said plug in jack J5 or J'5 in order to maintain ground on conductor 611 to prevent the deactivation of relay 658 and the consequent restoration of the wipers 635 to 638. When relay 658 deactivates, a circuit can be traced from grounded armature 628, armature 630, winding of relay 631, armature 632, off-normal springs to the release magnet Re6.

Calls have been detailed wherein the calling operator at jack J7' first gained the response of the said answering operator at jacks J7 and J7', the latter said operator then extending the call through selector E8 to telephone T19, or over line L9. It will now be assumed that the said answering operator will cause the said selector E8 to set its wipers 837 to 840 on bank contacts 882 to 885, respectively. Under the latter condition a talking path can be traced from the jack J7', line L7, inside armatures of relays 750 and 745, conductors 746-747, wipers 839-840, conductors 886-887, 522-523, inside armatures of relays 521 and 525, line L5 to jack J5'. Wiper 837 will apply ground to bank contact 882, conductors 612 and 611, armature 675 to the winding of relay 676, the latter said relay actuating. Armature 624 disconnects conductor 515 from the winding of relay 626. Armature 602 disconnects conductor 504 from the winding of relay 603. A circuit path can be traced from ground, winding of relay 612', sleeve of plug P'16, sleeve of jack J7', armatures 828, 829, wiper 838, bank contact 883, conductors 890, 680, armatures 618, 616, conductor 510, center point of line winding of repeating coil C'5, line L5, center point of line winding of repeating coil C5 to the sleeve of jack J5'. The upper armature of relay 676 will apply ground over conductor 891 to the winding of relay 512, cutting off drop D5.

If the calling operator at jack J7' applies signaling current in bridge of the talking conductors from source corresponding to

G16, it will operate drop D5' as a calling signal.

Upon a plug like P16 being inserted into jack J5' in responding, a circuit can be traced from ground, winding of relay corresponding to 601', sleeve of plug, sleeve of jack J5' and over the traced path to sleeve of jack J7', the winding of relay 710; the latter said relay operating to, in turn, operate relay 715 to cause lamp 108' to glow. Due to the calling switching plug being in jack J7', relays 722 and 714 will be actuated. The shunt path including resistance 770 will be open, so that the relay corresponding to 601' connected to sleeve of jack J5', will deactivate, due to its marginal characteristic, causing the lamp corresponding to 610' controlled thereby to extinguish as an answering signal. Due to armatures 624 and 602 being attracted, the selector D6 is barred from control from jack J5 or J5', so if an attempt is made to listen-in through either of the latter said jacks, the obstructing resistances 507 and 508 will restrict the speech currents abstracted from the connection, due to relay 615 being normal.

It will be clear that if the equipments to the left of section line B' (Fig. 5) be removed, and the equipments to the right of section line B (Fig. 9) be removed, and then the circuits to the right of section line B' be joined to the circuits to the left of section line B the sending of directive impulses from the calling device 607' of the cord-pair cooperative with the plug P'16 in jack J7' over the last traced path including conductor 510, will serve to progress the call through selector F9 in the manner before described. In this connection, it will be clear that spring 730 may be tied to the sleeve of its jack in lieu of to the key spring shown, and under the latter condition the key 766 and calling device 765 will be dispensed with, the relay corresponding to 601' or 612', as the case may be, of the cord-pair used will apply the ground through spring 730, in lieu of from spring 729. The calling device in the cord-pair will then be subject to being introduced, in lieu of the latter said relay, serially with the winding of relay 722 for directly controlling the selector E8 as was described with relation key 766 and calling device 765.

Assume that the city toll operator desires to extend a connection between telephone T19 of the local exchange and jack J10. Plug P2 will be inserted into jack J2, whereupon a circuit path can be traced from ground, winding of relay 201, spring 202, spring 203, sleeve of plug P2, sleeve of jack J2, conductor 205, series winding of marginal relay 301 to the winding of relay 302, the latter said relay actuating, but the relay 301 remaining inert. A circuit can be traced from grounded armature 305 to the winding of slow-releasing relay 306, the latter said relay actuating. Armature 307 will apply its ground through ar-

mature 308 to the winding of relay 309, the latter said relay actuating. Armature 312 on relay 306 applies ground to conductor 313. Relay 201 is not operatively energized, due to the high-resistance value of the winding of relay 302. The key D2 will be manipulated to substitute the winding of relay 201 by calling device CD2 in the traced path including relay 302.

Upon pulling digit "1" on the dial of the calling device CD2, the energizing circuit including relay 302 will be opened and closed as a directive impulse, whereby relay 309 will deactivate and reactuate one time, the relay 306 sustaining over the current lapse, due to the armature 305 retracting for the period of the impulse. When armature 315 retracts, it applies its ground through armature 316, winding of slow-releasing series relay 318, armature 319 to the winding of the vertical magnet VM3, the latter said magnet operating to step the wipers 321 to 326 into alignment with the first level of bank contacts. At the time relay 318 is energized, its armature 330 applies ground from conductor 313 to make-before-break spring 331, off-normal spring 333, conductor 334 to armature 336 and the lower winding terminal of relay 337 and through armature 338 to wiper 321. At the time spring 331 becomes grounded, an operative circuit path can be traced from said spring, winding of relay 339, armature 348 on the rotary magnet RM3 to grounded battery, the relay 339 actuating. This ground applied through armature 336, spring 333 to the upper winding terminal of relay 339 will form a locking path for relay 339 when ground is removed from spring 331 upon armature 330 retracting, and when the latter occurs, an operative path exists from the winding of the rotary magnet RM3, springs 331, 333, conductor 334, armature 336 to grounded conductor 313. The rotary magnet will operate to drive the wipers 321 to 326 into engagement with the first set of bank contacts 341 to 346, respectively, the energizing circuit for relay 339 opening at armature 348 to retract armature 336. If bank contact 341 constitutes busy ground, this will cause ground to be maintained on the lower winding terminal of relay 337, so its winding will remain short-circuited. When armature 348 retracts, an operative circuit can be traced from grounded battery thereon, winding of relay 339, spring 333, armature 338 to wiper 321 on grounded bank contact 341. When relay 339 reactuates, the rotary magnet will operatively energize over the before traced path through armature 336, as well as primarily through armature 338 to ground on bank contact 341, the wipers being step-advanced automatically until an idle set of bank contacts leading to a line of the group containing line L9 is encountered, whereupon,

the selector will seize in the manner as will appear.

Assuming that bank contact 341 does not constitute ground when tested, neither the 5 rotary magnet nor the relay 339 will re-energize, and ground will not be applied to the lower winding terminal of relay 337. However, an operative circuit can be traced from 10 grounded battery, armature 348, winding of relay 339, spring 333, winding of relay 337 to grounded conductor 313. The windings of relays 339 and 337 are thus energized in series, but due to the marginal adjustment of relay 339, it will remain inert, while relay 337 will 15 actuate to effect the seizure of selector B3.

After selector B3 seizes, a circuit can be traced from grounded armature 351, wiper 326, bank contact 346, common conductor 352 to the winding of the solenoid of the impulse 20 device H3. The plunger 354 will be drawn upwardly to apply a series of two ground impulses from bar 355, followed by the spaced single ground impulse over common conductor 356, bank contact 345, wiper 325, conductor 358, winding of slow-releasing relay 212 to the stepping magnet 213. The stepping magnet will thus drive the pointer 214 over the scale divisions, off-normal spring 215 being applied to ground consequent to the 25 first off-normal movement of the pointer 214. Due to the pause in the transmission of impulses following the second, relay 212 will retract its armature 216 so an operative circuit path can be traced from the release magnet 218, armature 216, off-normal spring 215 to ground, to restore the pointer. When the 30 third impulse is applied, the pointer will be driven over one scale division and forthwith restored. That is, the calling operator by observing the indicator will be apprised that the selector B3 actually seized the line L9, due to the peculiar set of impulses sent back effective to the pointer 214 of the indicating device H2. In this connection, it will be understood 35 that each line will have a device, such as H3, operative through bank contacts from all accessible switches, so when a line is seized, the calling operator receives a conformation not only of the fact the switch directly operated (switch B3 in the present instance) seized, but what line it seized, due to the specific impulse train sent effective to the indicating device corresponding to H2. It will, of course, be understood that the impulse 40 train from the line device corresponding to H3 may be arranged to send impulses corresponding numerically to the arbitrary number of the line, for ready identification, and in fact, the device H2 may preferably be dispensed with and conductor 356 attached permanently to line conductor 868 of line L9, for example, to create an audible tone disturbance in operator's set S2 corresponding to the said impulse train to indicate the fact that a specific line has been seized. Wiper 325 and

cooperating bank contacts will not now be required. The plunger-arm 354 clears the upper-most contact after engaging it, on the upward stroke, and is so maintained during the time the line is held. 70

The line L9 being now seized, a talking path can be traced from the tip and sleeve springs of jack J2, line conductors 221-222, armatures 223-224, conductors 225-226, armatures of relay 301, armatures 363-364, 75 wipers 323-324, bank contacts 348-344, conductors 867-868, repeating coil C9, line L9, repeating coil C'9, conductors 961-962 to armatures 964-963. A circuit path can also be traced from grounded armature 307, armature 308, wiper 322, bank contact 342, conductor 866, center of line winding of repeating coil C9, line L9, center of line winding of repeating coil C'9, conductor 901, armature 902 to the winding of relay 903, the latter said 80 relay actuating, followed by the actuation of relays 907 and 912, in the manner before described. Relay 306 remains energized from armature 305 so that ground from conductor 313 is applied through armature 338, wiper 90 90 321, bank contact 341, conductor 865 and multiplied bank contacts, to guard the line L9 against intrusion by accessible switches. 95

If the calling operator now pulls digit "1" on the calling device dial, relay 302 will de-actuate and reactuate one time, causing relays 903 and 907 to similarly function. In view of previous descriptions, the latter said functioning of relay 907 will cause the wipers 921 to 924 to be set upon and seize the first set of 100 idle bank contacts 941 to 944, respectively. Under the condition of selector F9 seizing, the path traced to the armatures 964-963 will be extended through wipers 923-924, bank contacts 943-944, conductors 58-59, repeating coil C10, line L10, repeating coil C'10 to jack J10. The path from armature 906 is extended over wiper 922, bank contact 942, conductor 950 to the winding of relay 3, the latter said relay and relay 4 actuating in the 105 manner before described to apply ground to operate relay 15 to in turn glow lamp 18 as a calling signal. Upon the call being responded to by inserting a plug, such as P16, into jack J10 (and, of course, the listening 110 keys L16 and L2 being operated) the calling and called operator will be in talking relation. 115

It will be further assumed that it is desired to connect the exchange line leading to telephone T19 with the line extension linked to jack J10. That is, the toll operator having jacks J2 and J'2 accessible desires to inter-connect jack J10 with telephone T19, and thereafter supervise the connection generally as if the line extension to jack J10 and the line to be extended to telephone T19 were to be conductively linked through a cord-pair as shown in Fig. 2, in lieu of through the interlinked pair of selector switches B3 and 120 125 130

C4. The latter said switches being located remotely with respect to the latter said cord-pair, it will appear that the operator in control of the latter said cord-pair need not 5 know the physical interlinking of the said switches B3 and C4, and may therefore possibly assume, so far as operating methods are concerned, that the connection established between J10 and T19 exists through 10 the latter said cord-pair as an actual link of the connection, in lieu of being a remote controlling agency for the link constituting said switches B3 and C4.

The calling operator will now insert plug 15 P'2 into jack J'2, whereupon a circuit path can be traced from ground, winding of relay 231, springs 232-233, sleeve of plug P'2, jack J'2, conductor 235, lower and upper windings of relay 401 to the winding of relay 402, the latter said relay actuating, but relay 401 remaining inert, due to its marginal adjustment. A circuit path can be traced from grounded armature 405 to the winding of slow-releasing relay 407, the latter relay actuating, its armature 408 applying ground to conductor 409. A circuit can be traced from ground, winding of slow-releasing marginal relay 412, armatures 413, 414 to the winding of relay 415, the latter two said relays actuating. The armature of relay 412 will short-circuit the lower winding of relay 401 and thus reduces the resistance included in the path including the winding of relay 231 to augment the current 25 traversing it to its operative value, so its armature will cause supervisory lamp 238 to glow. It will thus appear, presently, that when relay 412 reattracts its armature, and thus removes the short-circuit from the lower 30 winding of relay 401, the current traversing the winding of relay 231 will become attenuated below its operative value to extinguish lamp 238. The calling operator will operate key D'2 to introduce the calling device CD'2 35 in lieu of the winding of relay 231. Upon the operator pulling digit "2" on the calling dial of the device CD'2, the relays 402 and 415 will deactivate and reactivate two times responsive thereto. The relay 407 (also relay 412) will sustain over the lapses wherein armatures 405 and 413 retract two times. Armature 419 will thus apply two ground impulses through armature 420, winding of relay 416, armature 417 to the vertical magnet VM4, effective to step the wipers 421 to 424 into alignment with the second level of bank contacts.

Having in mind that the wiring and disposition of the five relays counting from 40 the right (including the rotary magnet and off-normal springs), in selectors B3 and C4 are alike, it will not be necessary to a complete disclosure of the operation of the selector C4 to detail the functioning thereof as to its wipers 421 to 424 rotating-in and

seizing the first set of bank contacts 431 to 434 leading to conductors 857 to 860, respectively, and thence to first selector F19, wherein wiper 421 will apply ground to conductor 857 and attached bank contacts as a busy 70 guard against switches normally having access thereto. The conductor 858 will be the impulse conductor over which selector F19 and succeeding switches will be directly controlled from the calling device CD'2 75 upon digits "11211" being sent to complete the connection to the line extending to T19 and automatically signal upon same.

The selectors F19, S19, N19 and connector C19 will function in the manner referred to before. That is, the calling operator, through listening key L'2, is in talking relation with the leading-in line conductors of connector C19 over the path from jack J'2, conductors 221-222, 225-226, 361-362, armatures 441-442, 443-444, wipers 423-424, bank contacts 433-434, conductors 859-860 and through corresponding conductors to connector C19. Upon the called party responding by removing the receiver from the switch-hook at telephone T19, the current traversing the said impulse conductor will be attenuated so that relay 412 will deactivate to remove the short-circuit from the lower winding of relay 401, to cause the lamp 238 85 to extinguish as an answering signal. Should the party at telephone T19 replace the receiver, the current will be again augmented in the path including the relay 412 to again short-circuit the lower winding of relay 401, whereby the relay 231 will again actuate to glow lamp 238 as a clearing signal. It is thus clear that a difference exists in the selectors B3 and C4 in that supervision is not applied to lamp 239, due to the high resistance value of the winding of relay 302. 90

It will be manifest that since the talking conductors 225-226 are common to the two branches of the extended connections to the called jack J10 and the line leading to called telephone T19, the latter said called stations will be in talking relation with each other. In order to prevent the currents constituting speech from being attenuated or dissipated because of electrostatic capacity, or low resistance multiple paths involving the extension of conductors 225-226 in the direction of the jacks J2 and J'2, the operator can, by closing key LP2, at will, apply ground over conductor 240 to the winding of relay 241, causing its armatures 223-224 to remove the short-circuit from resistances 241-242. Under the latter condition, the current abstracted from the station to station connection due to the leg including conductors 221-222 will be constrained to a reduced maximum, and therefore, will not seriously interfere with the conversation between the called stations while permitting the operator to audibly supervise through the operator's 100 105 110 115 120 125 130 135 140 145 150 155 160 165 - telephone set S2. The operator may, in lieu of operating key LP2, employ listening key L'2 in lieu of listening key L2. The listening connections of the two latter said keys are in multiple. However, an auxiliary spring set 245 is in multiple relation with the springs of key LP2, so the operation of key L'2 effects not only the same function as key L2, but that of key LP2 as well.
- 10 The switching operator can, at will, cut off either called station of the connection and converse secretly with the other station. For example, operating key C2 will apply minus grounded battery through spring 233, sleeve of plug P'2, sleeve of jack J'2, conductor 235, upper winding of relay 401, winding of relay 402 to plus grounded battery, relay 401 actuating to open the extension at armatures 441—442. Under the latter condition, only 15 the party at jack J10 will be in talking relation with the switching operator.
- If the switching operator manipulates key C'2, minus grounded battery through spring 203, sleeve of plug P2, sleeve of jack J2, conductor 205, winding of relay 301, winding of relay 302 to plus grounded battery will comprise an energizing circuit path, relay 301 actuating to open the extension at its armatures. Under the latter condition, only 20 the party at telephone T19 will be in talking relation with the switching operator. It will be noted that when key L2, L'2 or LP2 is operated, the relays 201 and 231 remain operatively related to the extension through selectors B3 and C4, respectively.
- 25 Attention is called that the two left-hand relays of selector B3 may be replaced by three relays as shown counting from the left of selector C4, and vice versa, without departing from the spirit of the invention. The said relay arrangement shown in selector B3 does not provide for varying the current strength in conductor 205, while the latter said relay arrangement in selector C4 provides for varying the current strength in conductor 235, as has been set forth.
- If, in lieu of setting the wipers of selector C4 on bank contacts 431 to 434, the wipers had been set upon bank contacts 451 to 454, 30 corresponding to line L7, the impulse conductor leading through armature 414 would lead through wiper 422 as before, but this time through bank contact 452, conductor 666, armatures 872, 805, conductor 712 to the winding of relay 710 and through shunting resistance 770, spring 771 to grounded battery. Thus, when a plug as P16 is inserted into jack J7' by way of a response, the shunt through resistance 770 is opened to cause relay 412 to retract its armature to in turn cause relay 231 to retract its armature to extinguish lamp 238. It is thus manifest that two toll lines may be interconnected and supervised through the companion selectors B3 and C4. Similarly, if the selector B3 has its
- wiper set upon a set of bank contacts corresponding to a local selector, such as one of the group containing selector F19, for example, and the call is then extended to a local line, such as one of the group containing the line leading to telephone T19, for example, two lines will be interconnected and supervised through the companion selectors B3 and C4.
- 35 The restoration of selectors B3 and C4 is controlled independently from jacks J2 and J'2, respectively. That is, withdrawing the plug from jack J2 will deenergize relay 302, which in turn will cause relays 309 and 306 to deactivate. A circuit can then be traced from ground, armatures 315, 316, winding of relay 318, armature 319, off-normal springs to the release magnet Re3. Withdrawing the plug from jack J'2 will deenergize relay 402, which in turn will cause relays 415 and 407 to deactivate. A circuit can then be traced from ground, armatures 419, 420, winding of relay 416, armature 417, off-normal springs to the release magnet Re4.
- 40 Having in mind that the selector B3 may be modified so the three left-hand relays (displacing the two left-hand relays) will correspond to the similarly situated relays in selector C4, it will be clear that the relay 201 and associated lamp 239 will operate like relay 231 and its associated lamp 238 controlled from the line terminating the extension through selector B3. In commercial embodiments, the selectors B3 and C4 will preferably be similar to selector C4 as drawn, but including also the auxiliary wipers (as 325—326) and connections shown in selector B3, so either selector may be used for extensions to a local or to a toll line, interchangeably.
- 45 Referring again to Fig. 4, the line device H4 is a generally similar line device to H3 in Fig. 3, but is designed to apply two spaced single impulses in lieu of two impulses and a spaced single impulse. Also, the said device H4 is directly associated with its corresponding line and not applied through the agency of a specific wiper set, as in Fig. 3. In the present instance, the said device H4 is associated with the line 15 leading to selector D6, there being a similar device for each 50 trunk of the group. When the conductor 612 becomes grounded from a switch seizing, the solenoid of the said device H4 will draw its plunger-arm 451 to apply ground-seeking tone from bar 452 through the contacts to conductors 453 and 887. Thus, the operator listening-in when the switch C4 seizes will perceive the tone through the corresponding talking wiper of the seizing switch. This, of course, not only applies to switch C4, but also to all other switches having access to line 55 15, as well; switch E8, for example.
- 55 It will be manifest that while the drawings show selectors remotely controlled from an answering operator's position local to the said

selectors, such as D6 and E8 on lines L5 and L6, respectively, the opposite (left-hand) ends of the said lines may be similarly equipped. Under this condition the calls will be progressed similarly from either end of a line. Of course, traffic and other conditions will determine the detailed commercial embodiment of the general organization of the present invention.

10 I claim:—

- responsive to the operation of the impulse contact only after the responded condition of the called line is effaced to re-initiate and thereupon sustainingly apply the signaling current to the called line while maintaining the previously established connection. 5
8. In a telephone system, a calling and a called line, a train of switches for linking a connection from the calling to the called line, a simplex circuit of the talking conductors of the calling line, an impulse contact for directively operating the switches over the simplex circuit, means for sustainingly applying signaling current to the called line responsive to establishing the connection, means to disconnect the said signaling current consequent to a response on the called line, and means controlled from the calling line over the simplex circuit responsive to the operation of the said impulse contact only after the responded condition of the called line is effaced to reinitiate and thereafter self-sustain the application of signaling current to the called line while maintaining the previously established connection. 15
9. In a telephone system, a calling and a called line, a train of switches for linking a connection from the calling to the called line, an operating link of the connection, an impulse contact of the operating link for directively operating the switches over the operating link, a source of current, means for self-sustainingly applying signaling current to the called line, means to disconnect the said signaling current consequent to a response on the called line, and means controlled responsive to the application of the said source of current to a talking conductor of the calling line and also means responsive to the operation of the impulse contact only after the responded condition of the called line has been effaced to reinitiate and self-sustain the application of signaling current to the called line while maintaining the previously established connection. 30
10. In a telephone system, a calling and a called line, a train of switches for linking a connection from the calling to the called line, an operating link of the connection, an impulse contact of the operating link for directively operating the switches over the operating link, a source of current of a character to which a condenser is transparent, means for self-sustainingly applying signaling current to the called line, means to disconnect the said signaling current consequent to a response on the called line, and means controlled responsive to the application of the said source of current to a talking conductor of the calling line and also means responsive to the operation of the impulse contact only after the responded condition of the called line has been effaced to reinitiate and self-sustain the application of signaling current to the called line while maintaining the previously established connection. 35
11. In a telephone system, a calling and a called line, a train of switches for linking a connection from the calling to the called line, an impulse conductor of the calling line, an impulse contact of the impulse conductor for operating the switches over the impulse conductor, a source of current, means for sustainingly applying signaling current to the called line, means to disconnect the said signaling current consequent to a response on the called line, means responsive to the application of the said source of current in bridge of the talking conductors of the calling line and also means responsive to the operation of the said impulse contact only after the responded condition of the called line has been effaced to reinitiate and self-sustain the application of signaling current to the called line while maintaining the previously established connection. 70
12. In a telephone system, a calling line, other lines, automatic switch mechanism, means operated over the calling line to cause the switch mechanism to extend the calling line into connection with one of said other lines, and a signal sending device individual to said latter line made effective responsive to said connection for transmitting a signal over the calling line to indicate the specific said other line connected to. 75
13. In a telephone system, a calling line, other lines, automatic switch mechanism, means operated over the calling line to cause the switch mechanism to extend the calling line into connection with one of said other lines, a signal device capable of displaying any of a plurality of indications, and a signal sending device individual to said other line connected with made effective responsive to said connection for transmitting impulses over the calling line to the signal device to indicate the specific said other line connected to. 80
14. In a telephone system, a pair of impulse controlled selective switches having a common talking path, a pair of jacks one for each said switches respectively, called lines, an operator's cord circuit with switching plugs, a source of signaling current, means for directively operating the switches from the cord circuit independently according to the respective jack seized to connect called lines over the common talking path whereby the said called lines thereby become connected for talking service directly through the said switches irrespective of any talking path including the jacks, and means for applying the signaling current through the jacks and through the corresponding switch to its connected called line. 100
15. In a telephone system, a pair of impulse controlled selective switches having a 110

- common talking path, a pair of jacks one for each said switches respectively, called lines, an operator's cord circuit with switching plugs, supervisory mechanism associated with the jacks, means for directly operating the switches from the cord circuit independently according to the respective jack seized to connect called lines over the common talking path whereby the said called lines thereby become connected for talking service directly through the said switches irrespective of any talking path including the jacks, and means for controlling the supervisory mechanism from the respectively called lines whereby the responded or non-responded state of the said called lines will be indexed. 16. In a telephone system, a pair of impulse controlled selective switches having a common talking path, a relay for opening the talking path of each said switch to the other said switch, a pair of jacks one for each of said switches respectively, called lines, an operator's cord circuit with switching plugs, means for directly operating the switches from the cord circuit independently according to the respective jack seized to connect called lines over the common talking path whereby the said called lines thereby become connected for talking service directly through the said switches irrespective of any talking path including the jacks, and means controlled through the said jacks respectively for disconnecting the talking path through the corresponding switch towards the called line seized by said switch, while maintaining the talking connection from the alternative jack with the called line connected through the companion switch. 17. In a telephone system, a pair of impulse controlled selective switches having a common talking path, a pair of jacks one for each of said switches respectively, called lines, an operator's cord circuit with switching plugs, means for directly operating the switches from the cord circuit independently according to the respective jack seized to connect called lines over the common talking path whereby the said called lines thereby become connected for talking service directly through the said switches irrespective of any talking path including the jacks, and means controlled from the jacks for restoring the respective switch from a connected called line. 18. In a telephone system, a pair of impulse controlled selective switches having a common talking path, a pair of jacks one for each said switches respectively, called lines, an operator's cord circuit with switching plugs, means for directly operating the switches from the cord circuit independently according to the respective jack seized to connect called lines over the common talking path whereby the said called lines thereby become connected for talking service directly through the said switches irrespective of any talking path including the jacks, and means for placing the cord circuit in talking relation with the called lines. 19. In a telephone system, a pair of impulse controlled selective switches having a common talking path, a pair of jacks one for each said switches respectively, called lines, an operator's cord circuit with switching plugs, means for directly operating the switches from the cord circuit independently according to the respective jack seized to connect called lines over a common talking path whereby the said called lines thereby become connected for talking service directly through the said switches irrespective of any talking path including the jacks, means for placing the cord circuit in talking relation with the called lines, and means for placing the cord circuit in attenuated talking relation with the called lines. 20. In a telephone system, a pair of impulse controlled selective switches having a common talking path, a pair of jacks one for each said switches respectively, called lines, an operator's cord circuit with switching plugs, and means for directly operating the switches from the cord circuit independently according to the respective jack seized to connect called lines over the common talking path whereby the said called lines thereby become connected for talking service directly through the said switches irrespective of any talking path including the jacks. 21. In a telephone system, a calling and a called line, a calling station on the calling line, a branch of the calling line, a switching station on the branch of the calling line said branch terminating in a jack, a directive switch on the calling line, an operator's switching cord cooperative with said jack, means whereby the directive switch can be operated over the branch to connect the calling and called lines, and means at the switching station including said cord operative at the will of the operator for setting-up a condition whereby destroying the established connection to the called line will thereafter reside in the calling station. 22. In a telephone system, a calling and a called line, a calling station on the calling line, a branch of the calling line, a switching station on the branch of the calling line said branch terminating in a jack, a directive switch on the calling line, an operator's switching cord cooperative with said jack, means whereby the directive switch can be operated over the branch to connect the calling and called lines, and means at the switching station including said cord operative at the will of the operator for opening the talking path between the calling station and the called line and to then hold a secret talking connection with the calling against the called lines.

- line while maintaining the said plug in its cooperative jack.
23. In a telephone system, a calling and a called line, a calling station on the calling line, a branch of the calling line, a switching station on the branch of the calling line said branch terminating in a jack, a directive switch on the calling line, an operator's switching cord cooperative with said jack, means whereby the directive switch can be operated over the branch to connect the calling and called lines, and means at the switching station including said cord operative at the will of the operator for opening the talking path and thereafter closing the talking path at a point intermediate of the calling station and the called line while maintaining the said plug in its cooperative jack. 75
24. In a telephone system, a calling and a called line, a calling station on the calling line, a branch of the calling line, a switching station on the branch of the calling line said branch terminating in a jack, a directive switch on the calling line, an operator's switching cord cooperative with said jack, means whereby the directive switch can be operated over the branch to connect the calling and called lines, and means controlled at will from the said cord through the jack for altering the talking relation to a minimum. 80
25. In a telephone system, a calling and a called line, a calling station on the calling line, a branch of the calling line, a switching station on the branch of the calling line said branch terminating in a pair of jacks, a directive switch on the calling line, an operator's switching cord cooperative with said jacks, supervisory apparatus in the cord circuit, means in the cord circuit whereby the directive switch can be operated over the branch to connect the calling and called lines, and means whereby the answered or normal state of the calling and called lines will be evidenced by a corresponding state of the supervisory apparatus. 85
26. In a telephone system, a calling and a called line, a calling station on the calling line, a branch of the calling line, a switching station on the branch of the calling line said branch terminating in a pair of jacks, a directive switch on the calling line, an operator's switching cord cooperative with said jacks, supervisory apparatus and directive apparatus in the cord circuit, means whereby the directive switch can be operated from the cord circuit over the branch from the cord circuit directive apparatus, means at the switching station including said cord circuit operative at will for holding a talking connection with one end of the connection secretly against the other end without destroying the connection, and means including the supervisory apparatus whereby the answered or normal state of the called line will be evidenced. 90
27. In a telephone system, a calling and a called line, a calling station on the calling line, a branch of the calling line, a switching station on the branch of the calling line said branch terminating in a jack, a directive switch on the calling line, an operator's switching cord cooperative with said jack, means whereby the directive switch can be operated over the branch to connect the calling and called lines, means at the switching station including said cord operative at the will of the operator for establishing a maximum talking relation therefrom commonly with calling station and the called line, and means controlled at will from the said cord through the jack for altering the talking relation to a minimum. 95
28. In a telephone system, a calling and a called line, a calling station on the calling line, a branch of the calling line, a switching station on the branch of the calling line said branch terminating in a jack, a retardation coil normally included serially in the talking path of the said branch, a directive switch on the calling line, an operator's switching cord cooperative with said jack, means whereby the directive switch can be operated over the branch to connect the calling and called lines, and means at the switching station including said cord for excluding the said retardation coil at the will of the operator. 100
29. In a telephone system, a calling and a called line, a train of switches for linking a connection from the calling to the called line, an operating link of the connection including an operator's switching cord and plug, an impulse contact of the operating link for directly operating the switches over the operating link, means for self-sustainably applying signaling current to the called line, means to disconnect the said signaling current consequent to a response on the called line, and means controlled responsive to the operation of the impulse contact only after the responded condition of the called line has been effaced to reinitiate and self-sustain the application of signaling current to the called line while maintaining the previously established connection. 105
30. In an automatic telephone system, a called line, a trunk link consisting of an operating conductor and a pair of talking conductors and having an automatic switch at its far end, an impulse contact of the trunk link operating conductor, means for operating the said link switch responsive to the directive operation of the impulse contact to extend the trunk into connection with the called line, means for sustainably applying signaling current to the called line, means controlled 110
- 115
- 120
- 125
- 130

from the called line by a response thereon for terminating the said application of a signaling current, and means responsive to operating the impulse contact only after the responded condition has terminated for reinitiating and self-sustaining the application of signaling current to the called line while maintaining the first established connection.

31. In an automatic telephone system, a calling and a called line, an operating conductor of the calling line, a pair of talking conductors of the calling line, a plurality of trunk links each link consisting of an operating conductor and a pair of talking conductors and having an automatic switch at its far end, an impulse contact of the calling line operating conductor, means including the said link switches responsive to directive operation of the impulse contact to extend the calling line over said links in tandem, means directly controlled over the extended operating conductor for in turn directly operating the farmost switch into connection with the called line, means for sustainingly applying signaling current to the called line, means controlled from the called line by a response thereon for terminating the said application of signaling current, and means responsive to operating the impulse contact only after the responded condition has terminated for reinitiating and self-sustaining the application of signaling current to the called line while maintaining the first established connection.

32. In a telephone system, a calling and a called line, a train of switches for linking a connection from the calling to the called line, an impulse contact of the calling line for operating the switches to effect the said connection, means for applying sustained signaling current from the last switch of the train to the called line controlled from a said switch antecedent thereto, a relay in the antecedent switch, means for actuating and locking the relay to disconnect the signaling current consequent to a response on the called line, means including the relay for preventing the reapplication of signaling current to the called line regardless of the termination of the responded condition of the called line, and means including the impulse contact for restoring the relay to reapply the signaling current to the called line while maintaining the first established connection.

33. In a telephone system, a calling and a called line, a train of switches for linking a connection from the calling to the called line, an impulse contact of the calling line for operating the switches to effect the said connection, means for applying sustained signaling current from the last switch of the train to the called line controlled from a said switch antecedent thereto, a relay in the antecedent switch, means for actuating and locking the relay to disconnect the signaling

current consequent to a response on the called line, a code switch operative responsive to the operation of the impulse contact, means including the relay for preventing the reapplication of signaling current to the called line regardless of the termination of the responded condition of the called line, and means including the impulse contact and the code switch for restoring the relay to reapply and automatically sustain the application of signaling current to the called line while maintaining the first established connection.

34. In an automatic telephone system, a calling and a called line, an automatic switch for completing a connection from the calling to the called line, a code switch, means for directly operating the automatic switch to effect the said connection, means for sustainably applying signaling current to the connected called line, means controlled over the connected called line for terminating the application of the signaling current without destroying the connection between the calling and the called lines, means for operating a circuit control contact of the code switch responsive to a predetermined directive one of a plurality of possible directive operations of the code switch for reinitiating the sustained application of signaling current to the called line, and means controlled over the calling line for operating the code switch to effect the operation of the said control contact while sustaining the first established connection.

35. In a telephone system, a calling and a called line, a switch for completing a connection from the calling to the called line, a code switch, means for directly operating the switch to effect the said connection, automatically applied means for sustainably applying signaling current to the connected called line, means controlled over the connected called line for terminating the application of the signaling current without destroying the connection between the calling and the called lines, means for operating a circuit control contact of the code switch responsive to a predetermined directive one of a plurality of possible directive operations of the code switch for reinitiating the sustained application of signaling current to the called line, and means controlled over the calling line for operating the code switch to effect the operation of the said control contact while sustaining the first established connection.

36. In an automatic telephone system, a calling station on a calling line, called lines, automatic switch mechanism for connecting the calling line to any one of said called lines, a signaling mechanism for each called line which will send identification signals specific to its companion line, and means automatically applied consequent to effecting a

- said connection to a called line for operating the signaling mechanism for sending a signal to the station to verify by signal the specific connection established.
- 6 37. In a telephone system, a calling station on a calling line, called lines, switch mechanism for connecting the calling line to any one of said called lines, a signaling mechanism for each called line which will
- 10 send identification signals specific to its companion line, means automatically applied consequent to effecting a said connection to a called line for operating the signaling mechanism for sending a signal to the station to verify by signal the specific connection established, and automatically applied means for preventing the signal from being continuously reapplied.
- 20 38. In an automatic telephone system, a calling station on a calling line, called lines, an automatic switch mechanism for connecting the calling line to any one of said called lines, a signaling mechanism individual to each called line, and means automatically applied consequent to effecting a said connection to a called line for operating the associated signaling mechanism for sending a signal to the station to verify by signal the specific connection established.
- 25 39. In a telephone system, a calling station on a calling line, called lines, a switch mechanism for connecting the calling line to any one of said called lines, a signaling mechanism individual to each called line, means automatically applied consequent to effecting a said connection to a called line for operating the associated signaling mechanism for sending a signal to the station to verify by signal the specific connection established.
- 30 40. In a telephone system, a calling station on a calling line, called lines, a switch mechanism for connecting the calling line to any one of said called lines, a signaling mechanism individual to each called line, means automatically applied consequent to effecting a said connection to a called line for operating the associated signaling mechanism for sending a signal to the station to verify by signal the specific connection established, and automatically applied means for preventing the signal from being continuously reapplied.
- 45 41. In an automatic telephone system, lines, a pair of impulse controlled selective switches having a common talking path, an operator's switchboard, a pair of leading-in talking conductors extending between the switchboard and the said common talking path of the switches, automatic means whereby the switchboard operator can at will independently operate and restore the respective switches with relation to a directly called one of said lines, means for selectively operating the switches to connect two said lines over the said common talking path regardless of the said pair of conductors, and automatic means operated from the switchboard to directly disconnect one or the other of the connected said lines so that the said pair of conductors will then be exclusively connected in talking relation with the called line not disconnected without restoring either said switch from its connected called line, and means for reestablishing the connection between the two called lines without again connectively operating a said switch of the connection.
- 50 42. In a telephone system, lines, a pair of impulse controlled selective switches having a common talking path, a leading-in trunk for the said switches, automatic means for independently selectively operating the switches to connect the said common talking path with two said lines to form a Y talking connection between the said two lines and the said trunk, and means controlled over the trunk for applying and thereafter at will disconnecting signaling current independently to one or the other connected said line.
- 55 43. In a telephone system, called lines, a trunk line and terminating pair of automatic switches, means for independently operating the switches over the trunk line to establish a Y talking connection between two said lines and the trunk line, and means controlled over the trunk line to disconnect one or the other called line branch at will without destroying the remaining called line branch connection while maintaining the switches operated.
- 60 44. In a telephone system, called lines, a trunk line and terminating pair of automatic switches, means for independently operating the switches over the trunk line to establish a Y talking connection between two said lines and the trunk line, means controlled over the trunk line to disconnect one or the other called line branch at will without destroying the remaining called line branch connection and for restoring the said Y connection without reoperating a said switch.
- 65 45. In a telephone system, called lines, a trunk line and terminating pair of automatic switches, means for independently operating the switches over the trunk line to establish a Y talking connection between two said

lines and the trunk line, an obstructing resistor, a relay, and automatic means including the relay for at will excluding and including the resistor in the talking path of 5 the trunk line while leaving the talking path between the called lines unobstructed.

46. In a telephone system, first, second and third stations, a first link joining the first and second stations, a second link joining 10 the first link and third station forming a Y talking connection of the stations, a resistor, and automatic means for introducing the resistor in the second link to reduce the audition only between the third station and the 15 other said stations while the audition between the first and second stations will remain normal.

47. In a telephone system, lines, a pair of switches, a common talking circuit of the 20 switches, a leading-in trunk to the said talking circuit, means for operating the switches independently to connect each switch to a said line to form a Y talking connection between the connected lines and the trunk, a 25 resistor for the trunk, and automatic means for introducing the resistor in the trunk to reduce the audition only between the trunk and the other branches of the connection while the audition between the connected said 30 lines remains normal.

48. In a telephone system, a pair of automatic switches having a common talking path, a pair of jacks one for each said 35 switches respectively, called lines, an operator's circuit, an operator's switching cord and plug, supervisory mechanism, an impulse conductor for each switch and corresponding jack, means for independently operating the 40 switches over the respective impulse conductor and jack from the operator's circuit and through the said cord and plug to connect two called lines in talking relation over the said common talking path, means for effecting and effacing a responded condition of 45 the respective called lines, and means including the supervisory mechanism and corresponding impulse conductor for indicating to the operator the said responded and said effected state of the specific called lines. 50

49. In a telephone system, a calling and a called line, a branch of the calling line, a switching station on the branch, a directive switch on the calling line, means whereby the 55 said switch can be automatically operated over the branch to extend the calling line to the called line, means controlled only from the said switching station for destroying the 60 established connection with the called line, means at the switching station for setting up a condition whereby destroying the established connection to the called line will thereafter reside in the calling station, and automatically applied means effective incidental 65

to destroying the said connection which will disable the last said means.

50. In a telephone system, a calling and a called line, a branch of the calling line, an operator's station on the branch, a directive 70 switch on the calling line, a resistor serially included intermediate of the calling line and the said branch for obstructing current only over the branch, means whereby the directive switch can be automatically operated to 75 extend the calling line to the called line to form a Y talking connection between the calling line the called line and the operator's station, and means controlled at will from the operator's station for excluding and restoring the resistor. 80

51. In a telephone system, a calling and a called line, a branch of the calling line, an operator's station on the branch, a directive 85 switch on the calling line, a resistor serially included intermediate of the calling line and the said branch for obstructing current only over the branch, means whereby the directive switch can be automatically operated to 90 extend the calling line to the called line to form a Y talking connection between the calling line the called line and the operator's station, and automatic means for excluding and restoring the resistor. 95

52. In a telephone system, a calling and a called line, a branch of the calling line, an operator's station, a resistor serially included intermediate of the calling line and the said branch for obstructing current only 100 over the branch, means for connecting the operator's station to the said branch, means controlled from the operator's station whereby the directive switch can be automatically operated to extend the calling line to the called line to form a Y talking connection between the calling line and the called line and the branch, and means automatically applied incidental to connecting the operator's station to the branch for excluding the resistor. 105

53. In a telephone system, a calling and a called line, a branch of the calling line, an operator's station on the branch, a resistor intermediate of the calling line and the branch, a directive switch on the calling line, means whereby the directive switch can be automatically operated to extend the calling line to the called line to form a Y talking connection between the calling line the called line and the branch, automatic means controlled over the branch for excluding the resistor, and automatic means controlled from the operator's station for at will disconnecting the calling or the called line and for thereupon maintaining a secret talking connection over the said branch with the connected said line and against the said disconnected said line. 110

54. In a telephone system, a calling and a called line, a branch of the calling line, an operator's station on the branch, a resistor 115

- intermediate of the calling line and the branch, a directive switch on the calling line, means whereby the directive switch can be automatically operated to extend the calling line to the called line to form a Y talking connection between the calling line the called line and the branch, automatic means controlled over the branch for excluding the resistor, automatic means controlled from the operator's station for at will disconnecting the calling or the called line and for thereupon maintaining a secret talking connection over the said branch with the connected said line against the said disconnected said line, and supervisory means at the operator's station for simultaneously denoting the responded or non-responded condition of the calling and called lines during the said disconnection.
55. In a telephone system, a calling and a called line, a branch of the calling line, an operator's station, a resistor serially included intermediate of the calling line and the said branch for obstructing current only over the branch, means for connecting the operator's station to the said branch, means controlled from the operator's station whereby the directive switch can be automatically operated to extend the calling line to the called line to form a Y talking connection between the calling line and the called line and the branch, automatic means controlled over the branch for excluding the resistor, and automatic means controlled from the operator's station for at will disconnecting one of the said lines and for thereupon maintaining a secret talking connection over the said branch with the connected said line and against the said disconnected said line.
56. In a telephone system, a calling and a called line, a branch of the calling line, an operator's station on the branch, a directive switch on the calling line, a resistor serially included intermediate of the calling line and the said branch for obstructing current only over the branch, means whereby the directive switch can be automatically operated to extend the calling line to the called line to form a Y talking connection between the calling line the called line and the branch, and automatic means controlled from the operator's station over a talking conductor of the branch for at will excluding the resistor.
57. In a telephone system, three stations in talking relation over a Y branched connection, a resistor serially included intermediate of one said branch for obstructing current only over said one branch, and automatic means controlled over a talking conductor of said one branch for excluding the resistor.
58. In a telephone system, a plurality of stations in talking relation over a star branched connection, a resistor serially included intermediate of one said branch for obstructing current only over said one
- branch, and automatic means controlled over a talking conductor of said one branch for excluding the resistor.
59. In a telephone system, a plurality of line extensions in talking relation over a star branched connection, a resistor serially included intermediate of one said branch for obstructing current only over said one branch, and automatic means controlled over a talking conductor of said one branch for excluding the resistor.
60. In a telephone system, a calling and a called line, automatic switch mechanism, a pair of talking conductors of the calling line, an operating conductor of the calling line companion to the said talking conductors but electrically nonconnected therewith, means to operate the switch mechanism over the operating conductor to extend a connection from the calling to the called line, means for sustainingly applying signaling current to the called line from the switch mechanism, means on the called line for disconnecting the signaling current, and means thereafter responsive to a changed condition of the operating conductor to again sustainingly reapply signaling current to the called line while maintaining the first established connection.
61. In a telephone system, a calling and a called line, automatic switch mechanism, a pair of talking conductors of the calling line, an operating conductor of the calling line companion to the said talking conductors but electrically nonconnected therewith, means to operate the switch mechanism over the operating conductor to extend a connection from the calling to the called line, means for sustainingly applying signaling current to the called line from the switch mechanism, means on the called line for disconnecting the signaling current, and means thereafter responsive to a changed condition of the operating conductor to again apply signaling current to the called line while maintaining the first established connection.
62. In a telephone system, a calling and a called line, automatic switch mechanism, an impulse device serially included in a derived path of a talking conductor of the calling line, means for at will manually setting the impulse device to thereafter directly operate the switch mechanism over the calling line to extend a connection from the calling line to the called line, means for sustainingly applying signaling current to the called line from the switch mechanism, means on the called line for disconnecting the signaling current, and means thereafter responsive to a changed condition on the calling line effective to the said serial path to again sustainingly reapply signaling current to the called line while maintaining the first established connection.
63. In a telephone system, a calling and a called line, automatic switch mechanism, an

operator's switching cord and plug circuit, an impulse device for serial inclusion in the said circuit, a jack for the calling line, said plug and said jack being cooperative, means for 5 manually setting the impulse device to thereafter directly operate the switch mechanism to extend a connection from the calling line to the called line, means to sustainingly apply signaling current to the called line 10 from the switch mechanism, means on the called line for disconnecting the signaling current, and means thereafter responsive to a changed condition in the said circuit for again sustainingly applying signaling current 15 to the called line while maintaining the first established connection.

64. In an automatic telephone system, a trunk line, a called line, automatic switch mechanism, an impulse contact, means for 20 directly operating the switch mechanism over the trunk line responsive to the contact to selectively pair the trunk line with the called line, first and second sources of signaling current, automatically applied means for 25 causing said first source to be applied to the called line incidental to effecting said selection of the called line, means controlled over the called line for disconnecting said first source from the called line, and means then 30 responsive to applying said second source over the trunk line including a condenser in series with the path of the current from said second source and also means responsive to the impulse contact for again applying said 35 first source to the called line while maintaining the first established parity of said lines.

65. In a telephone system, a trunk line, a called line, switch mechanism, a calling device contact for directly operating the 40 switch mechanism into connection with the called line for pairing the trunk line with the called line, automatically applied means for continuously applying signaling current to the called line, means controlled over the 45 called line for terminating the application of said signaling current, and means responsive to a specific series and not responsive to a specific other series of operations of the calling device contact for at will again continuously applying signaling current to the called line without restoring the switch mechanism from connection with the called line.

66. In a telephone system, a trunk line, a 55 called line, switch mechanism, a relay of the switch mechanism, a first source of current, an impulse contact, means including said contact the winding of said relay said source of current and a conductor including a simplex 60 circuit of the trunk line in series for directly operating the switch mechanism to extend a connection from the trunk line to the called line, a source of signaling current, and means controlled by the relay operated by the 65 impulse contact to apply the source of signal-

ing current to the called line without destroying said connection with the called line.

67. In a telephone system, a calling line and other lines, a directive calling device on the calling line, a selective switch for completing a connection to a called one of said other lines under control of the calling device, and means operated consequent to the called line becoming seized to automatically apply and disconnect tone of specific character 75 with respect to the calling line, the character of the tone being determined by the specific line called.

68. In a telephone system, a calling line and other lines, a directive calling device on the calling line, a selective switch for completing a connection to a called one of said other lines under control of the calling device, and means made operative consequent to the called line becoming seized to automatically apply a pre-determined series of tone applications specific 80 in character audible on the calling line, the character of the tone series being determined by the specific line called.

69. In an automatic telephone system, a calling line, a called line, an automatic switch on the calling line, a branch of the calling line, means of control for operating and restoring the switch only over the branch, means on the branch for changing the control 95 from the branch to the calling line, and means controlled from the calling line for restoring the switch control to only said branch control.

70. In an automatic telephone system, a calling line, a called line, an automatic switch on the calling line, a branch of the calling line, means of control for operating and restoring the switch only over the branch, means on the branch for changing the control 100 from the branch to the calling line, and means controlled from the calling line for again having the said control of the restoring only from said branch. 105

71. In an automatic telephone system, a calling line, a called line, an automatic switch on the calling line, a branch of the calling line, means of control for operating the switch only over the branch, means on the branch for changing the control from the branch to the calling line, and means responsive to exercising said control from the calling line for thereupon returning the control to only 110 the branch.

72. In an automatic telephone system, a calling line, a called line, an automatic switch on the calling line, an intermediate station on the calling line, means of control for operating the switch only from the station, means at the station for changing the control 115 from the station to the calling line, and means responsive to exercising said control from the calling line for thereupon returning the control to only the station.

73. In an automatic telephone system, 130

called lines, a trunk line, a pair of selective switches terminating said trunk line, an operating conductor auxiliary to the trunk line individual for each said switch, a common 5 talking path for the switches, means for operating the switches independently to connect the two said called lines by the respective switches, means whereby the said connected called lines will thereby become connected in 10 talking relation over the common talking

path, and means independent of said trunk line conductors for releasing and reoperating the respective said switches independently of each other the last said means including the operating conductor corresponding to the 70 switch or switches released and reoperated.

In witness whereof, I hereunto subscribe my name this twenty-fifth day of October, A. D. 1922.

called lines, a trunk line, a pair of selective switches terminating said trunk line, an operating conductor auxiliary to the trunk line individual for each said switch, a common 5 talking path for the switches, means for operating the switches independently to connect the two said called lines by the respective switches, means whereby the said connected called lines will thereby become connected in 10 talking relation over the common talking

path, and means independent of said trunk line conductors for releasing and reoperating the respective said switches independently of each other the last said means including the operating conductor corresponding to the 70 switch or switches released and reoperated.
